KNITTING MACHINE

Howard S. Bridges, Sr., Hickory, N. C., assignor of fifty percent to Midway Hosiery Mills, Inc., Hickory, N. C., a corporation of North Carolina

Application March 7, 1955, Serial No. 492,665

28 Claims. (Cl. 66—155)

This invention relates to circular independent needle knitting machines and, more especially to improvements in knitting machines designed for producing separately knit variegated patches in tubular fabrics wherein sutures are formed at the junctures of adjacent areas. Although not limited thereto, the present invention is specifically concerned with improvements in knitting machines of the type known as a Model AA series manufactured by H. E. Crawford Company Inc., Kernersville, North Carolina.

It is an object of this invention to provide a circular knitting machine embodying the principles of the Crawford Model AA series of machines wherein novel controls and pattern means are provided for controlling the various yarn feeding and needle controlling elements of the machine resulting in a more compact and efficiently operating machine than the machines heretofore in use and facilitating ease of access to the various operating parts of the machine.

It is another object of this invention to provide a machine of the character described or a similar machine with a relatively large auxiliary pattern drum mounted for rotation about a vertical axis about the lower portion of the knitting machine preferably on a level below the lower end of the usual sock horn so that all of the complex mechanically operated elements of the machine are disposed above the level of the auxiliary pattern drum and whereby the auxiliary pattern drum may be of an extremely large diameter and height so that substantially all of the cams for controlling the various needle operating and yarn feeding elements of the machine are positioned on a single drum thereby simplifying the preparing of the pattern on the drum as well as insuring a more accurate response of the various knitting instrumentalities in predetermined sequence.

It is still another object of this invention to provide novel means for imparting step-by-step rotation to the relatively large pattern drum positioned about the lower portion of the circular knitting machine and wherein a novel form of vertically extending pattern bar is employed for controlling the intervals in which step-by-step rotation is imparted to the auxiliary pattern drum. Means are also provided for automatically imparting upward or active movement to the pattern bar at predetermined intervals to position rows of projections or pattern pins thereon at operating level in predetermined order and according to a predetermined pattern.

Some of the objects of the invention having been stated, other objects will appear as the description proceeds, when taken in connection with the accompanying drawings, in which—

Figure 1 is a front elevation of the improved circular knitting machine;

Figure 2 is a right-hand side elevation of the improved knitting machine looking at the right-hand side of Figure 1 with the improved vertical axis lower auxiliary pattern drum broken away;

Figure 3 is an enlarged elevation of the central portion of Figure 2;

Figure 14 is an enlarged elevation of the upper central portion of Figure 1.

Figure 15 is a sectional plan view taken substantially along line 15—15 in Figure 14;

Figure 16 is a somewhat schematic plan view similar to Figure 15, but omitting many of the parts which are mounted on the bed plate of the machine for purposes of clarity;

Figure 17 is an elevation partially in section taken substantially along line 17—17 in Figure 15, showing the yarn feed fingers and the upper portions of the thrust rods controlled by the main pattern drum, but being on a reduced scale;

Figure 18 is an elevation of the control means for the main yarn clamping and cutting mechanism, taken substantially along line 18—18 in Figure 15, but omitting many of the parts for purposes of clarity;

Figure 19 is a fragmentary vertical sectional view taken substantially along line 19—19 in Figure 11 showing the pattern controlled means which renders the means for imparting oscillation to the widening pick feed cams operative and inoperative;

Figure 20 is a view similar to Figure 15, omitting the sinker head and latch ring and being taken on a slightly lower level in Figure 11 than Figure 12;

Figure 21 is a somewhat schematic plan view of the entire machine taken substantially along the same level as Figure 12, but omitting most of those parts of the machine carried by the circular bed plate, the circular bed plate being shown in phantom lines;

Figure 22 is an enlarged fragmentary vertical sectional view taken substantially along line 22—22 in Figure 1 showing means for absorbing the shock of downward movement of the vertically movable pattern bar as it drops after having been released at the end of an upward stroke thereof;

Figure 23 is a fragmentary elevation looking at the right-hand side of Figure 22;

Figure 24 is a fragmentary elevation, on a reduced scale, showing the first row of cams on the main pattern drum in the left-hand portion of Figure 9;

Figures 25 to 34, inclusive, are schematic sectional views through the main pattern drum showing the succeeding ten rows of cams thereon adjacent the first row shown in Figure 24, reading from left to right in the upper left-hand portion of Figure 12;

Figure 35 is a schematic sectional view through the main pattern drum showing the last cam mounted on the periphery of the right-hand portion of the main pattern drum in Figure 9;

Figure 36 is a somewhat schematic view through the main pattern drum showing a cam plate fixed on the outer end thereof for controlling the releasing of the elongated pattern element, bar or rack when the latter has reached the upper limit of active movement thereof;

Figures 37 to 50, inclusive, are somewhat schematic plan views of the improved auxiliary pattern drum showing the successive rows of cams thereon reading from the uppermost to the lowermost portions of the improved pattern drum;

Figure 51 is an enlarged fragmentary isometric detail of the structure shown in the upper left-hand portion of Figure 7, showing the means for supporting and guiding the improved pattern drum;

Figure 52 is a somewhat schematic developed view showing the needle controlling cams as though looking outwardly from the needle cylinder and also showing the upper portions of some of the needles adjacent the latch ring.

Brief synopsis of the machine

The present invention principally resides in improved pattern mechanisms for controlling the various needle operating cams and the yarn feeding mechanism of a circular independent needle knitting machine and, by way of illustration, the present invention is shown in association with a knitting machine of the type manufactured by H. E. Crawford Company, Inc., Kernersville, North Carolina, and wherein many of the parts thereof are adapted from a machine of the type made by Scott & Williams under their Model Number B-5 and substantially as shown in the patent to R. W. Scott, No. 1,152,850 of September 7, 1915.

The knitting instrumentalities; that is, needle controlling cams and the yarn feeding, clamping and cutting means, as well as the shogging means for the needle cylinder and many other elements of the present machine are substantially the same as disclosed in a catalogue entitled "Crawford Argyle Knitting Machine Catalogue Models AA." Accordingly, many of the parts which are clearly illustrated in said catalogue or in said Scott patent and which are also used on the present machine will not be described in detail, for purposes of brevity.

The present machine employs much of the conventional type of driving and clutch mechanisms of said patent for shifting from rotary to reciprocatory knitting and vice versa. Also, the present machine includes the usual type of main cam shaft having a conventional pattern chain and cam drum thereon for controlling the clutch mechanism.

The usual type of needle cylinder having latch needles which move in individual slots in the periphery of the needle cylinder, is provided. The needle cylinder is driven, at times, to rotate and, at other times, to reciprocate and a conventional type of sinker head is provided with conventional sinkers therein which are controlled by conventional cams in a sinker cap associated therewith.

All of the above-named elements are substantially as disclosed in said Scott Patent No. 1,152,850 and many of the remaining elements of the machine disclosed in the present application are substantially the same as those of the Crawford machine and, accordingly, many specific

details, such as those pertaining to the arrangement of the butts of the latch needles, the specific manner in which the needle controlling cams are constructed, etc. have been omitted from the present drawings and a detailed description thereof is deemed unnecessary.

The present invention resides in a novel cam drum or auxiliary pattern drum mounted on a vertical axis below the driving and clutch mechanisms of the knitting machine and wherein a novel pattern controlled substantially vertically pattern bar is provided for controlling step-by-step movement of the improved auxiliary pattern drum or pattern cylinder, thereby greatly simplifying the setting up of the pattern for controlling the various knitting instrumentalities of the machine.

Referring to Figures 1 to 11, inclusive, 13 and 19, the machine generally comprises a main base or frame 100 supported on suitable legs 101 to 104, inclusive. The main base or frame 100 supports a vertically disposed upper cast frame 105 having spaced vertically disposed standard portions 105a, 105b for supporting the usual driving and clutch mechanisms to be later described. The machine has a conventional needle cylinder 106 which carries therein a plurality of vertically movable latch needles (Figures 11, 14, 20 and 52).

The latch needles are generally designated at N (Figure 52) and are the conventional type under alternate ones of which conventional jacks J are disposed. Of course, the jacks J are employed in making the welt or top of a stocking and all of the needles N cooperate with the usual sinkers in drawing stitches. Sinkers, not shown, are mounted in a sinker head 110 (Figures 14 and 16) and are controlled by suitable cams disposed in the cap of the sinker head in the usual manner. A latch ring 113 is provided which is mounted at the upper end of the needle cylinder 106. The needle cylinder 106 extends through a conventional circular bed plate or cam plate 114 suitably secured to the upper surface or side deck 105c of the cast frame 105 (Figures 8, 10, 14, 15, 18 and 21). The circular bed plate 114 supports the various needle cams, the yarn feed fingers, the clamping and cutting mechanisms and various other parts which will be later described.

A reduced portion 115 depending from the circular bed plate 114 (Figures 11 and 18) has the upper end of a conventional sock horn 116 loosely mounted therein. The lower end of the sock horn is loosely mounted in a circular guide member 117 suitably secured to the main base or frame 100. The sock horn 116 is raised and lowered by conventional means including a crank arm 120 (Figure 8) having conventional adjustment screws therein which are adapted to bear against corresponding circularly arranged cam members 121 (Figure 12) fixed on a conventional main pattern drum or cam drum 122 rotatably mounted on a shaft 123. Crank arm 120 (Figure 8) is oscillatably mounted on a shaft 124 and the shafts 123, 124 are fixed to the cast frame 105 (Figures 8 and 12).

Machine drive

Referring to Figures 1, 2, 3, 8, 10, 11, 12, 13 and 19, there is shown a conventional type of gearing usually associated with a machine of a type manufactured by Scott & Williams under their Model No. B-5 and which is similar to that appearing in said Scott Patent No. 1,152,850. Means are provided for transmitting rotation to the needle cylinder 106 and for shogging the needle cylinder, which means is substantially identical to the conventional Crawford machine and, accordingly, only a brief description will be given as to the structure and manner of operation of the means for imparting rotation to the needle cylinder.

As best shown in Figure 12, a sleeve bearing or bushing 126, fixed in the standard portion 105b of the cast frame 105, has a high speed pulley 127 rotatably mounted thereon. A pinion 128 integral with pulley 127 meshes with a gear 130 for imparting a normal or high rate of speed

to the needle cylinder 106 through intervening connections to be presently described. A tubular shaft 131 journaled in the bearing 126 has a conventional slow speed pulley 132 and a manually operable handle 134 fixed on the outer end thereof. A conventional idler pulley 137 is journaled on the hub of the slow speed pulley 132 and is driven by a constantly moving belt 140.

Belt 140 is shifted among pulleys 127, 132, 137 by a conventional automatically and manually operable forked shifter 141 (Figures 3 and 12) mounted for sliding movement on a shaft 143 fixed in the front portions of the standards 105a, 105b of the upper cast frame 105. The shifter 141 is normally urged inwardly by a conventional spring 142.

The gear 130 is fixed to the outer face of a gear 139 fixed on a shaft 144 journaled in the standard 105b of cast frame 105. The inner end of shaft 144 has a gear 145 fixed thereon which meshes with a pinion 146 fixed on the left-hand end of the tubular shaft 131 in Figure 12.

A reduced end portion 152 of a main drive shaft 153 is journaled in the left-hand end of tubular shaft 131. The shaft 153 is also journaled in the standard 105a. The usual type of clutch 154 is keyed on shaft 153, has sliding movement thereon and is shifted for alternate engagement with the pinion 146 and a pinion 155 by means of a shifting member 156 which is controlled as to position by conventional means including a clutch control cam drum 157 having suitable cams 160 thereon (Figures 11 and 12). The clutch control cam drum 157 is journaled on a shaft 161 journaled in the upper cast frame 105, this shaft 161 also having a ratchet wheel 162 loose thereon to which step-by-step movement is imparted by conventional means, not shown in the present drawings but being clearly shown and described in said Patent No. 1,152,850 (see Figure 13). The ratchet wheel 162 is controlled by a conventional pattern chain 163 (Figures 1, 2, 6, 7, 11, 12 and 13).

The pattern chain 163 has rows of predeterminedly spaced radially projecting cams, lugs or projections 164, 165 thereon. The lugs 164 control step-by-step rotation of the ratchet wheel 162 in exactly the manner disclosed in said patent and the lugs 165 on pattern chain 163 control step-by-step rotation of a widening pick feed cam pattern drum 166 (Figure 8), in a manner to be later described. The pattern drum 166 controls the operation of conventional widening pick feed cams also to be later described. Of course, as disclosed in said patent, the ratchet wheel or rack wheel 162 imparts rotation to the clutch control cam drum 157 according to a predetermined pattern for correspondingly imparting either reciprocatory or rotary movement to the needle cylinder 106.

The pattern chain 163 is mounted on a sprocket wheel 167 fixed on shaft 161 and having a ratchet wheel 170 integral therewith (Figures 11 and 12). Ratchet wheel 170 is also driven in a conventional manner as is clearly shown in Figure 5 of said patent (see Figure 13 of the present drawings). The pattern chain 163 is also mounted on a plurality of sprocket wheels 171 (Figure 2) journaled on a vertically disposed frame or plate 172 disposed between the legs 101, 102 of the machine and depending from an improved auxiliary pattern drum or cam drum supporting plate or platform 173 (Figures 1, 2, 3, 6, 7, 8, 9, 10, and 21) which is of substantially greater diameter than the dimensions of the machine frame and supports the improved relatively large auxiliary pattern drum or cam drum to be later described. It will be observed in Figure 6 that the platform 173 has suitable openings 174 therein through each of which one of the legs 101 to 104, inclusive, extends. It will also be observed in Figures 6 and 7 that the auxiliary pattern-drum-supporting platform 173 is spaced substantially below the main base 100 and depends therefrom by means of suitable screws 175 and spacing sleeves 176, there being four of the screws 175 and sleeves 176 shown in Figure 6.

When the clutch 154 (Figures 11, 12 and 13), under

control of pattern chain 163, is moved into engagement with the pinion or gear 146 rotary motion is transmitted to the shaft 153. On the other hand, when the clutch 154 is moved to the left in Figure 12 into engagement with pinion 155, reciprocatory motion is transmitted to the shaft 153 by the pinion 155, since pinion 155 is engaged by a reciprocating quadrant or segmental gear 184 loosely mounted on the portion of shaft 123 disposed between the standards 105a, 105b of the upper case frame 105. Continuous oscillation is imparted to quadrant 184 by a link 186 pivotally connected at opposite ends thereof to the quadrant 184 and the gear 145 (Figures 12 and 13), all of which is clearly shown in said patent.

A conventional bevel gear 187 is rotatably mounted adjacent the left-hand end of shaft 153 (Figures 8, 11, 12 and 19), and is, at times, driven in fixed relation to the shaft 153 by a shogging mechanism similar to that currently in use in the said Crawford machine and which will be later described in detail. The bevel gear 187 drives the needle cylinder 106 through a conventional bevel gear 188 (Figure 11) which is a usual part of the needle cylinder as is clearly shown in Figure 12 of said patent.

Means for shogging the needle cylinder

As it is well known in the art, in order to produce triangular or rectilinear areas in knitted fabric, wherein junctures of adjacent area or sutures may extend at an angle relative to the wales and courses being knitted and wherein adjacent areas are knit from separate yarns, the needle cylinder is shogged at predetermined intervals to cause a portion of the needles in the needle circle to move equidistant past the knitting station in knitting a first portion of a stocking during reciprocatory knitting, for example. Then, the needle cylinder is shogged so as to cause either the opposite group of needles in the needle circle to move equidistant past the knitting station or to cause another group needles, possibly including some of the needles in the first group along with additional needles from the second group to move equidistant past the knitting station.

The needle cylinder shogging means of the present application is quite similar to that currently in use on the so-called Crawford machines. It has already been stated how the bevel gear 187 in Figures 8, 11, 12, 13 and 14 is engaged by bevel gear 188 for transmitting rotation to the needle cylinder 106 from shaft 153. However, since the bevel gear 187 is loose on the shaft 153, the shogging clutch means or shogging mechanism is provided which comprises a shogging disk or wheel 200 which is fixed on shaft 153 and is disposed closely adjacent to or bears against a locking disk 201 suitably secured to the inner surface of the bevel gear 187.

At times, the shogging disk or wheel 200 rotates on shaft 153 relative to the locking disk 201 and the gear 187 and, most of the time, the shogging disk 200 is locked in fixed relation to the locking disk 201.

To this end, the locking disk 201 is provided with a plurality of circularly arranged predeterminedly spaced notches 203 in its periphery (Figure 12) which are adapted to be engaged in predetermined order, according to a predetermined pattern, by a locking finger, clutch finger or latch 204 oscillatably mounted, as at 205, on the periphery of the shogging disk 200. It will be noted that the locking finger 204 is substantially L-shaped in plan and is urged in a clockwise direction in Figure 12 by a tension spring 206. Thus, the locking finger 204 is normally urged into engagement with any one of the notches 203 in the periphery of the locking disk 201. This causes rotation or oscillation to be transmitted to the needle cylinder from the shaft 153. A brake mechanism, to be later described, prevents rotation of gear 187 during rotation of the shogging disk 200 relative to the locking disk 201.

In order to produce a shogging effect between the shogging disk 200 and the locking disk 201 of the shogging

clutch, which will, in turn, be transmitted to the needle cylinder 106, automatic pattern controlled means are provided, to be presently described, for momentarily releasing the locking finger 204 from engagement with a corresponding notch 203 in the locking disk and for subsequently permitting the locking finger 204 to again move into engagement with another of the notches 203. Referring again to Figure 12, it will be observed that the inner surface of the locking finger 204 is engaged by a radial clutch rod or pin 207 mounted for radial sliding movement in the shogging disk or wheel 209 and which penetrates a portion of the shaft 153 and enters a cavity or bore 210 provided in the left-hand end of the shaft 153. A spring pressed latch actuating pin 211 is mounted for axial movement in the bore 210 and is provided with a cavity forming a cam surface 213 therein which is normally urged out of engagement with the inner end of the pin 207 by a compression spring 214. The outer or left-hand end of the spring-pressed pin 211 engages one arm of a bell crank 215 pivoted at 216 on the lower end of a post 216 (Figures 8 and 11) suitably secured to and depending from the upper bed or needle cam plate 114. The spring 214 also urges this arm of bell crank 215 against a hand-release lever 217 which normally bears against the sock horn 116. Lever 217 is pivoted on a bracket 218 (Figures 11 and 12) fixed to sock horn 116.

The other arm of said bell crank 215 has the front end of a link 2-d pivotally connected thereto whose rear end is pivotally connected to a crank arm 2-c (Figure 9) fixed on the medial portion of an upright control shaft 2, there being a plurality of such upright control shafts designated at 1 to 14, inclusive. The control shafts 1 to 14, inclusive, are collectively arcuately arranged at the rear of the machine as best shown in Figures 6, 8, 9 and 21. These control shafts 1 to 14, inclusive, are peculiar to the present invention and are oscillatably mounted in upper and lower arcuate guide plates 222, 223. It will be observed in Figures 11 and 13 that the standards 105a, 105b of the upper cast frame 105 support the auxiliary bed plate or side deck 105c and it will be best observed in Figures 15, 20 and 21 that the upper arcuate guide plate for the substantially vertically disposed control rods or shafts 1 to 14, inclusive, has a pair of forwardly projecting arms 224, 225 thereon.

The front end of arm 224 is suitable secured to the rear portion of the circular bed plate 114 and the front end of the arm 225 is suitably secured to the upper surface of a pattern bar guide supporting bracket 226 which is, in turn, suitably secured to the upper surface of the auxiliary bed plate 105c. The front portion of the lower arcuate control rod guide plate 223 is suitably secured to the upper surface of the lower auxiliary pattern drum supporting platform 173 (Figures 6 and 9).

The lower ends of the improved vertically disposed control shafts or rods 1 to 14, inclusive, have respective cam follower arms 1-a to 14-a, inclusive, thereon which may also be termed as cam reading arms or control fingers. The control fingers 1-a to 14-a, inclusive, are adapted to, at times, engage the periphery of the improved lower auxiliary pattern drum broadly designated at 230 and, at other times, the control fingers 1-a to 14-a are adapted to be engaged by corresponding cams 1-b to 14-b, respectively, suitably secured to the periphery of the improved lower auxiliary pattern drum 230.

The cams 1-b to 14-b are best shown schematically in the respective Figures 37 to 50, inclusive. It will be observed in Figure 9 that the lower end portions of the four control rods or shafts 7, 8, 9 and 10 are loosely mounted in an auxiliary guide plate 231 and the lower portions of the control rods or shafts 11, 12, 13 and 14 loosely penetrate an auxiliary guide plate 232. The auxiliary guide plates 231, 232 are spaced substantially below the lower guide plate 223 and are supported thereby, by means of screws or bolts 233, 234, whose enlarged medial

portions maintain the auxiliary guide plates 231, 232 in proper spaced relation below the lower guide plate 223.

Since the lower auxiliary pattern drum 230 constitutes one of the most important features of the present invention it will be more fully described later in this context in order to establish a clear line of demarcation between the elements which constitute the present invention and those elements which do not constitute parts of the present invention.

Knitting instrumentalities

The knitting instrumentalities, including the needle and jack control cams, the yarn feed fingers, the latch ring, the clamping and cutting mechanisms for the inelastic and elastic yarns and, as a matter-of-fact substantially all of the parts mounted upon the circular bed plate 114 are shown as being conventional parts of a Crawford Model AA type of knitting machine and are substantially as disclosed in said knitting machine catalogue. Accordingly, only so much of the knitting instrumentalities will be described as is necessary to provide a clear understanding as to how certain of the knitting instrumentalities are controlled by the improved lower auxiliary pattern drum 230. The knitting cams (Figure 52) will be first described.

Reading from right to left in Figure 52, vertically spaced upper and lower stationary needle leveling cams 240, 241 are spaced above a portion of a needle guide cam 243 which partially surrounds the lower portion of the needle cylinder 106 and is suitably secured to the inner surface of a cam cylinder or ring 244 carried by the upper circular bed plate 114. To the left of the needle guide cam 243 in Figure 52 a jack lowering cam 246 is provided, the proximal portions of the needle guide cam and the jack lowering cam 246 being cut away to provide an inverted substantially V-shaped opening therein in which a jack advancing cam 247 is disposed for raising the needle jacks J. Of course, alternate needles have conventional jacks disposed in vertical alignment therewith for raising them to take the elastic yarn R during the knitting of an elastic top of a stocking.

Disposed between the proximal ends of the needle guiding cam 243 and the jack lowering cam 246 is a jack guiding ring 250 which is also suitably secured to the cam cylinder or ring 244. Disposed to the left of the upper and lower needle leveling cams 240, 241 is a right-hand widening pick feed cam 13-e which is disposed above a portion of a first elevating switch cam 14-e. The cams 13-e, 14-e are radially movable and are so designated, since they are controlled, through intervening connections, by the respective cams 13-b, 14-b on the improved lower auxiliary pattern drum 230 (Figures 49 and 50).

The right-hand widening pick feed cam 13-e, which is normally spring-biased outwardly relative to the needle cylinder by conventional means, not shown, is also moved inwardly to operative position, at times, by a feed cam actuating arm 251 (Figure 15) which is controlled as to oscillation by novel means to be later described. Referring again to Figure 52, it will be observed that a pair of right-hand widening picks 252, 253 are disposed immediately to the left of the right-hand widening pick feed cam 13-e. Disposed to the left and below the lower level of the right-hand widening pick 253 is a welt needle lowering cam 254 which is normally spring-biased outwardly and is normally out of the path of travel of all the needles in the needle circle, but is adapted to engage the butts of alternate needles raised by the jacks J in knitting the elastic top or welt of a stocking. The welt needle lowering cam 254 is controlled by the main pattern drum or cam drum 122, as will be later described.

A second elevating switch cam 12-e is disposed to the left of the right-hand widening pick 253 and the welt needle lowering cam 254 in Figure 52 and above the level of the welt needle lowering cam 254. A portion of a

first needle lowering switch cam 11-e is disposed above the second elevating switch cam 12-e and these cams 11-e, 12-e, which are also normally spring-biased outwardly, are controlled by the respective rows of cams 11-b, 12-b (Figures 47 and 48) on the improved lower auxiliary pattern drum 230.

Disposed to the left of the first lowering switch cam 11-e in Figure 52 is a set of conventional stitch cams defining a knitting station and including cams 256 to 259, inclusive. The set of stitch cams 256 through 259 is mounted on the cam plate or circular bed plate 114 in a conventional manner and is disposed centrally of an opening defined by upwardly diverging upper surfaces of a pair of spaced conventional hardened cams 263, 264 which serve to return the butts of any needles which may be passed into the opening defined thereby to a mean horizontal plane.

A segmental needle support race 265 is disposed to the left of the left-hand hardened cam 264 and its left-hand end terminates in engagement with the corresponding end of the needle guiding cam 243. The upper surfaces of the cam 243 and race 265 are disposed on the same level. Right-hand and left-hand variable capacity narrowing picks broadly designated at 266, 267 cooperate with the stitch cams 258, 259 in the usual manner and, disposed to the left and above the level of the left-stitch cam 259 is a stationary auxiliary needle leveling cam 270 which is also suitably supported on the circular bed plate 114. A pair of left-hand widening picks 271, 272 are disposed to the left of the auxiliary needle leveling cam 270 and a left-hand widening pick feed cam 273 is disposed to the left of the left-hand narrowing picks 271, 272. The left-hand widening pick feed cam 273 is also spring-biased outwardly and is controlled only by the feed cam actuating arm 251 (Figure 15).

The feed cam actuating arm 251 functions to alternately move the right-hand and left-hand widening pick feed cams 13-e, 273 into and out of operative position. A second needle lowering switch cam 8-e, which is spring-biased inwardly, is spaced below the left-hand widening pick feed cam 273 and is so designated, since it is controlled by the cams 8-b (Figure 44) on the improved lower auxiliary pattern drum 230. This completes the description of the needle and jack controlling cams shown in Figures 15, 20 and 52.

The machine is also provided with a special movable sinker control cam 275 (Figure 16) which is controlled by the main pattern or cam drum 122 to move outwardly into operative position simultaneously with inward movement of the welt needle lowering cam 254 (Figure 52). The special movable sinker control cam 275 operates upon the butts of the sinkers during the knitting of the elastic top of a stocking in substantially the same manner as that shown and described in U. S. Patent No. 2,420,771 issued to Herman E. Crawford on May 20, 1947 to assist in producing a ribbed effect in the top of the stocking. The controls for cams 254, 275 will be later described.

The upper and lower needle leveling cams 240, 241 are supported on a post 280 fixed to the circular bed plate 114 and whose upper portion limits oscillatory movement of the sinker head 110 in a conventional manner (Figures 15, 16 and 20). The right-hand widening pick feed cam 13-e and the first elevating switch cam 14-e are mounted for radial movement relative to the needle cylinder 106 in a block 281 fixed to the circular bed plate 114 (Figures 14 and 20). The welt needle lowering cam 254 is mounted for radial movement in a block 282 (Figures 16 and 20) fixed to the circular bed plate 114.

The first needle lowering switch cam 11-e and the second elevating switch cam 12-e are mounted for radial sliding movement in a block 285. The left-hand widening pick feed cam 273 and the second needle lowering switch cam 8-e are mounted for radial movement in a block 286 suitably secured to the circular bed plate 114. The manner in which the needle cams are mounted in

the blocks 281, 282, 285, 286 is clearly illustrated in said knitting machine catalogue and a detailed description thereof is deemed unnecessary. Each of the widening picks 252, 253, 271, 272 has a capacity for lowering two needles into action and each is universally mounted for oscillation about a substantially vertical and a substantially horizontal axis in a corresponding post. The posts for picks 252, 253 and 271, 272 are respectively designated at 287, 287' (Figures 15 and 20). The posts 287, 287' are mounted for vertical movement in respective brackets 290, 290' fixed to the circular bed plate 114.

The brackets 290, 290' have respective upwardly projecting guide plates 291, 291' thereon which are suitably notched for guiding the corresponding widening picks so their inner ends move downward in the course of outward movement thereof and so that they move upwardly in the course of inward movement thereof in the manner well known in the art and as disclosed in said catalogue.

It will be noted that the outer ends or stems of the widening picks 252, 253 and 271, 272 ride upon the upper edges of the respective guide plates 291, 291'. Movable adjacent the respective guide plates 291, 291' are respective slide cams 292, 292' which are also suitably notched so that, at times, the notches therein register with the notches in the respective guide plates 291, 291' and, at other times, they close either of the notches or both of the notches in the respective guide plates 291, 291' in a conventional manner, with the result that the widening picks 252, 253, 271, 272 are selectively rendered inactive although they may be swung inwardly by arms 293, 293' (Figure 15) carried by the feed cam actuating arm 251. The slide cams 292, 292' are controlled by the main pattern drum 122, as will be later described.

It will be noted that the blocks 287, 287' in which the inner right-hand and left-hand widening picks 252, 271 are mounted have respective abutments or angle clips 294, 294' thereon which are alternately engaged by the respective arms 293, 293' (Figures 15 and 20) for swinging the inner ends of the latter widening picks 252, 271 inwardly as the respective widening pick feed cams 13-e, 273 are permitted to move outwardly by oscillation of the feed cam actuating arm 251. It will also be noted in Figures 15 and 20 that the stems of the widening pick feed cams 13-e, 273 have respective upwardly projecting abutments 300, 300' thereon whose respective outer surfaces are engaged by inwardly biased L-shaped dogs 301, 301' pivotally mounted on opposite ends of the feed cam actuating arm 251 and which are biased inwardly by springs 302, 302'.

Thus, oscillation of the feed cam actuating arm 251 about a vertical axis (Figure 15) alternately causes the widening pick feed cams 13-e, 273 to move inwardly momentarily to operative position and to then move outwardly to inoperative position as shown in Figure 20. Whenever the widening picks 252, 271 are swung inwardly in the manner heretofore described, they also cause the inner ends of the outer widening picks 253, 272 to move inwardly, since the outer ends or stems of the inner widening picks 252, 271 have respective screws or rods 304, 304' (Figure 20) fixed thereto which extend outwardly and bear against the stems of the respective widening picks 253, 272.

Oscillation is imparted to the feed cam actuating arm 251 at predetermined intervals according to a predetermined pattern. To this end, it will be observed in Figure 1, 8, 14, 15 and 20 that the feed cam actuating arm 251 is fixed on the upper end of a vertically disposed shaft 306 journaled in a bearing 307 fixed to the front surface of the circular bed plate 114. The lower end of shaft 306 has a crank 310 (Figure 8) fixed thereon which extends rearwardly and has one end of a link 311 pivotally connected thereto. The link 311 extends outwardly to the right in Figures 1, 14 and 21 and is pivotally connected to the front end of a lever 312 pivot-

ally mounted, as at 313, (Figures 3 and 21) on the side deck 105c of the cast frame 105.

The rear end of lever 312 has follower arm 314 (Figures 3 and 4) pivotally mounted thereon and extending inwardly therefrom. The pivoted follower arm 314 has a follower or roller 135 on its inner end and extends into the open outer end of a racking cam drum 317 which rotates a complete revolution with each revolution of the needle cylinder 106. The inner surface of the racking cam drum 317 has a pair of circularly spaced frusto-triangular cams 320, 320' fixed thereon (Figures 3, 4 and 5) whose respective outer and inner edges are staggered so they alternately impart outward and inward movement to the follower 315 and follower arm 314 when the follower 315 is in raised or operative position, all of which is clearly shown on Page 25 of said catalogue. The follower 315 is urged into the neutral position between the cams 320, 320', as indicated by the broken line in Figure 5, due to the outwardly biased widening pick feed cams 13-e, 273, which, as shown in Figure 15, normally maintained the widening pick actuating arm 251 in neutral position.

The raising and lowering of the inner end of the pivoted follower arm 314 into and out of operative position relative to the cams 320, 320' in the racking cam drum 317 is peculiar to the present invention, although the raising and lowering of the inner end of the follower arm 314 may be carried out in a conventional manner as disclosed on Page 25 of said catalogue. In this instance, the inner portion of the follower arm 314 rests upon a substantially L-shaped lifting lever 321 pivotally connected at its rear end to the outer arm of a bracket 322 which is substantially U-shaped in plan (Figures 10 and 21). Said arm of bracket 322 supports the outer end of the shaft 317a (Figures 4, 12 and 13) on which the racking drum 317 is rotatably mounted.

The inner end of shaft 317a is fixed in the lower end of an inverted substantially L-shaped bracket 323 whose upper horizontal portion (Figures 13 and 21) extends forwardly and is suitably secured to the upper surface of the side deck 105c of the upper cast frame 105 immediately adjacent the vertical pattern bar guide supporting bracket 226 heretofore described. It will be observed in Figures 2, 3 and 21 that the U-shaped bracket 322 extends rearwardly and then inwardly and then forwardly and again inwardly and the latter portion thereof is suitably secured to the rear surface of the vertical leg of the inverted L-shaped bracket 323 (Figure 13).

The inner forwardly projecting leg of the bracket 322 is reinforced by means of a diagonal brace 325 whose upper end is connected to the rear portion of the inner forwardly projecting leg of bracket 322 (Figures 10 and 21) and which extends downwardly and forwardly at an angle and has its lower portion in Figures 2, 3 and 13 suitably secured to a bearing block 326 which is, in turn, suitably secured to the rear edge of the main base 100. The racking drum 317 is a conventional part of the machine, although three rows of axially spaced circularly arranged cams 330, 331, 332 are mounted on the periphery thereof, which cams are peculiar to the present invention.

As will be more fully described hereafter, the spaced cams 330 (Figures 3, 9, 10 and 21), at times, impart movement to means which control the intervals in which the machine operates at high and slow speeds and intervals during which the improved lower auxiliary pattern drum 230 is racked. The second or middle row of cams 331 on the racking drum 317 also impart oscillation to a pawl, to be later described, for imparting step-by-step movement to the lower auxiliary pattern drum 230 and the row of cams 332 on the racking drum 317 impart oscillation to a ratchet pawl, also to be later described, for racking the vertically movable pattern bar, also to be later described.

Referring again to the lifting lever 321 shown in Fig-

ures 2, 3, 9 and 10 it will be observed that the lower end of a link 335 is pivotally connected to the lifting lever 321. The upper end of link 335 is pivotally connected to the outer end of a crank arm 336 which, as best shown in Figures 9, 10, 14 and 21, extends inwardly and is fixed on the rear end of a horizontal rocker shaft 337 journaled in rear and front bearing blocks 340, 341. The rear bearing block 340 is fixed to, or integral with, the horizontal portion of bracket 323 and the front bearing block 341 is suitably secured to the side deck 105c of the upper cast frame 105. The front end of the rocker shaft 337 has a crank arm 342 fixed thereon which extends inwardly and has the upper end of a link 343 pivotally connected thereto (Figures 3, 13 and 14).

The lower end of a link 343 is pivotally connected to one end of a lever or crank 344 whose elongated hub is oscillatably mounted, as at 345, on the standard 105a of the upper cast frame 105. Said hub also has a crank or lever 344a thereon which has the upper end of a link 346 pivotally connected thereto (Figures 1, 11, 12, 14 and 19). The lower end of link 346 (Figures 8, 11 and 19) is pivotally connected to the outer or front end of a cam follower lever or arm 347 oscillatably mounted intermediate its ends on the shaft 143 (Figures 8, 11, 12, 13 and 19) and the rear portion of the follower lever 347 engages either the periphery of the widening pick pattern drum or wheel 166 or circularly arranged cams 351 thereon. The widening pick control pattern drum or wheel 166 is mounted and controlled in a conventional manner, substantially as is disclosed on pages 31 and 39 of said catalogue.

The pattern wheel 166 is driven intermittently in a step-by-step manner according to the desired pattern and is controlled as to its intermittent movement by the lugs 35 or projections 165 heretofore described on the conventional pattern chain 163 (Figure 11) and through intervening connections. The intervening connections between the pattern wheel 166 and the lugs 165 on pattern chain 163 include a ratchet wheel 352 (Figures 8 and 19) which is integral with pattern wheel 166. The pattern wheel 166 and the ratchet wheel 352 are rotatably mounted on the left-hand end of the shaft 161 in Figure 11. In order to prevent free rotation of the pattern wheel 166 and ratchet wheel 352 on shaft 161, a suitable friction means is provided in the form of a leaf spring member 353 having a friction member 354 (Figure 11) thereon which is urged against the outer surface of pattern wheel 166 by the leaf spring member 353.

The front portion of leaf spring member 353 is suitably secured to the medial portion of an upright bracket 355 (Figures 8, 11 and 19) suitably secured to one side of a post 356 whose lower end is fixed to the front edge of the main base 100.

A ratchet pawl 357, pivotally mounted adjacent the upper end of a pawl-carrying arm 358, is normally urged into engagement with the ratchet wheel 352 by a tension spring 360. The upper end of tension spring 360 is connected to the medial portion of pawl 357 and the lower end thereof is connected to the medial portion of pawl-carrying arm 358. Referring to Figure 19, it will be observed that the upper end of the pawl-carrying arm 358 has a hook portion 361 integral therewith which normally engages a restraining latch 362 which extends forwardly and is pivotally mounted on the upper end of bracket 355.

The lower end of the pawl-carrying arm 358 is fixed on one end of a stub shaft 65 oscillatably mounted in the upper end of post 356. The other end of shaft 365 has the front end of a bar 367 fixed thereon, to the rear end of which a bunter 368 is secured. The free end of bunter 368 is disposed in the same vertical plane as the quadrant 184. The bunter 368 is normally urged upwardly at its rear end or right-hand end in Figure 19 by a tension spring 371, the lower end of which is connected at the juncture of bunter 368 with arm 367 and the upper end

of which is connected to the medial portion of a follower arm 372.

The free front end of follower arm 372 is provided with a follower stud 373 thereon (Figures 11 and 19) disposed in the vertical plane of the lugs 165 on the pattern chain 163. Thus, the tension spring 371 urges the follower stud 373 and the bunter 368 toward each other and, in so doing, urges the hook portion 361 of the pawl-carrying arm 358 outwardly or forwardly in the event of the restraining latch 362 being raised out of engagement with said hook portion 361. Movement of the pawl-carrying arm 358 and the bunter 368 in a counterclockwise direction in Figure 19 is limited by the medial portion of bunter 368 engaging the hub of the sprocket wheel 167 on which pattern chain 163 is mounted.

It will be observed in Figure 11 that the follower arm 372 extends rearwardly and to the left from the follower stud 373 and then rearwardly again and is integral with or suitably secured to a hub 376 to which the rear end of a latch lifting arm 377 is also suitably secured. The latch lifting arm 377 has the upper end of a link 378 pivotally connected thereto, whose lower end is pivotally connected to the rear end of the restraining latch 362 (Figures 11 and 19).

In operation, upon any one of the lugs 165 on pattern chain 163 engaging the follower stud 373, the follower arm 372 and latch lifting arm 377 are moved in a clockwise direction in Figure 19 to thereby lift the restraining latch out of engagement with the pawl-carrying arm 358. Assuming the quadrant 184 to be elevated substantially above the position shown in Figure 19, it is apparent that the spring 371 then causes the bunter 368, the pawl-carrying arm 358 and the ratchet pawl 357 to move in a counterclockwise position so that, upon subsequent downward movement of the quadrant 184 in Figure 19, the quadrant engages bunter 368 to cause ratchet pawl 357 to advance the ratchet wheel 352 to rack the pattern wheel 166 one tooth. This will be repeated until the corresponding projection 165 (Figure 11) on pattern chain 163 moves out of engagement with the follower stud 373, whereupon the restraining latch 362 will then return to the position shown in Figure 19 to prevent further step-by-step movement of the ratchet wheel 352 and the widening pick pattern wheel 166.

Upon any one of the cams 351 (Figure 8) being in engagement with the control finger 347, the follower arm lifting lever 321 (Figure 2) assumes a lowered position so the follower 315 on arm 314 (Figures 1, 3, 4 and 21) is not engaged by the cams 320, 320' in the racking drum 317 during rotation thereof. The manner in which rotation is imparted to the racking drum 317 will be presently described. On the other hand, when the control lever or finger 347 drops into any one of the notches defined between adjacent cams 351 on the pattern wheel 166, the lever or arm 321 is moved upwardly in Figures 2, 3 and 4, as will be presently described, to move the follower arm 314 upwardly to where follower 315 will be engaged by the cams 320, 320' in the racking drum 317 to impart oscillatory movement to the lever 312 in Figure 21.

The lever or arm 321 is moved upwardly in Figures 2, 3 and 4 whenever the control finger 347 drops into any one of said notches defined between adjacent cams 351 on the pattern wheel 166, since this causes the front end of control finger 347 (Figures 8 and 21) to move upwardly to, in turn, raise the link 346 along with the crank 344a (Figure 14) to thereby cause the crank 344 to move downwardly along with link 343 and arm 342. This causes the horizontal rocker shaft 337 to move in a counterclockwise direction in Figure 14 to raise the free-end of crank arm 336, along with link 335 and lever 321 (Figures 2, 3 and 9) to thereby raise the follower 315 on follower arm 314 into the circular path of travel of the cams 320, 320' in the racking drum 317.

Since the widening pick feed cams 13-e, 273 are spring-biased outwardly in a conventional manner, it is apparent that this normally causes the feed cam actuating arm 251 (Figure 15) to assume a neutral position which, in turn, normally causes the cam follower 315 to assume a neutral position. The cams 320, 320' (Figures 4 and 5) in the racking drum 317 alternately engage the inner and outer surfaces of the follower 315 to alternately impart inward and outward movement to the cam follower 315 in a conventional manner, substantially as shown on page 25 of said catalogue. Thus, with oscillation of the lever 312 in Figure 21, it is apparent that, whenever the follower arm 314 is in raised or active position, oscillation is imparted to the feed cam actuating arm 251 to alternately move the widening pick feed cams 13-e, 273 into and out of operative position. Of course, as heretofore described, this also oscillates the arms 293, 293' to alternately swing the sets of widening picks 252, 253 and 271, 272 inwardly.

The racking drum 317 is a conventional part of a model AA Crawford machine and is driven in a conventional manner to rotate a complete revolution with each revolution of the needle cylinder 106. To this end, it will be observed in Figure 12 that the shaft 317a, on which the racking drum 317 is loosely mounted, has a gear 385 loosely mounted thereon which is fixed to the inner end of the racking drum 317 and this gear 385 engages gear 139. Since gear 139 is continuously driven at either high or slow speed during operation of the machine, it is apparent that continuous rotation is imparted to the racking drum 317 at a speed corresponding to that of the needle cylinder 106.

Step-by-step rotation is imparted to the main pattern drum or cam drum 122 in unison with step-by-step movement of the pattern chain 163 by conventional means as shown in said Patent No. 1,152,850 and including a gear 390 fixed on the inner end of the main pattern drum 122 which meshes with an idler gear 391 suitably journaled on the standard 195a of the upper cast frame 105. The gear 391, in turn, meshes with a gear 392 (Figures 11 and 19) fixed on the shaft 161 adjacent the pattern wheel 166 and on which shaft the sprocket wheel 167 which supports pattern chain 163 and the ratchet wheel 170 are fixedly mounted (Figures 8 and 11).

Yarn feeding means and yarn clamp and cutter means

The yarn feeding means for both the elastic and inelastic yarns and the clamping and cutting means of the present machine are substantially as conventionally used on the Crawford Model AA machines and substantially as shown on pages 19 and 21, respectively, of said catalogue. The present machines differ from the conventional Crawford machine, with respect to the yarn feeding means and the clamping and cutting means, only as to the improved lower auxiliary pattern drum 230 and the connections between the yarn feeding means and the clamping and cutting means and the improved lower auxiliary pattern drum 230. In the prior Crawford machines, a separate pattern drum, not used on the present machine, was employed for controlling the operation of the yarn feed fingers and the clamping and cutting devices.

In this instance, a plurality of main or inelastic yarns Y are drawn from individual packages or cones 400 and an elastic or rubber yarn R is drawn from a cone or package 401 (Figures 1 and 2). The cones or packages 400, 401 are supported on a conventional platform 402 spaced above the level of the circular bed plate 114 and having its front portion fixed on a post 403 whose lower end is suitably secured to the upper arcuate guide 222 (Figures 2, 3 and 21). The post 403 also has a plurality of arms 404 fixed to the upper portion thereof on which suitable tensioning devices 405, of the disk of the type are mounted and through each of which one of the yarns Y and R passes.

The elastic yarn R then extends downwardly and forwardly at an angle from the corresponding disk type ten-

sion device 405 (Figures 1 and 2) through a guide 406 (Figure 15) fixed to and projecting outwardly from the latch ring 113, and from whence the elastic yarn extends inwardly and passes through the usual eye of a conventional elastic yarn feed finger 407. The elastic yarn feed finger 407 is normally urged inwardly or forwardly to operative position by a tension spring 410 (Figure 15) and is slidably mounted in a block 411 fixed to an arm 412 which extends outwardly and is fixed to the upper end of a post 413 to which the latch ring 113 is pivotally connected, as at 414 (Figures 14 and 15).

The lower end of post 413 is suitably secured to the side deck 105c of the cast upper frame 105. The block 411 (Figure 15) also has a conventional scissors type clamp and cutter mechanism generally designated at 415 thereon and, since the elastic feed finger 407 and the clamp and cutter mechanism 415 are conventional and are controlled by the main pattern drum 122 in a conventional manner, and the present invention is concerned primarily with the improved lower auxiliary pattern drum 230 and its connections with the various knitting instrumentalities, a detailed description of the elastic yarn feed finger 407 and the clamping and cutting means 415 for the elastic yarn R is deemed unnecessary. The feed finger 407 and clamp and cutter means 415 are also controlled by the improved pattern drum 230.

It might be stated, however, that the outer end of the stem of the rubber or elastic yarn feed finger 407 is connected, by means of a pliable element or chain 416, to a crank 417 fixed on one end of a shaft 420 (Figures 15 and 20). Shaft 420 is journaled in a bearing block 421 fixed on a bracket 422 suitably secured to the rear portion of the side deck 105c of the upper cast frame 105. The other end of said shaft 420 has a crank 423 fixed thereon (Figures 15, 20 and 32) from which a pin 424 projects. The pin 424 bears against the upper end of a thrust rod 425 (Figure 32) mounted for vertical sliding movement in a pair of guides 426, 427 suitably secured to fixed parts of the machine.

The lower end of thrust rod 425, at times, bears against the periphery of the main pattern drum 122 and, at other times, the thrust rod 425 is engaged by a segmental cam 430 fixed on the main pattern drum 122 so that, when the cam 430 is in engagement with thrust rod 425, the elastic yarn feed finger 407 occupies inoperative position and, when the thrust rod 425 is engaged by the periphery of pattern drum 122, the spring 410 (Figure 15) moves the elastic yarn feed finger 407 into operative position for feeding the elastic yarn R to any of the needles N elevated by corresponding jacks J as they ride up the jack advancing cam 247 (Figure 52).

The elastic yarn clamp and cutter mechanism 415 normally clamps the elastic yarn R in the usual manner and, by comparing Figure 31 with Figure 32 it will be observed that a cam 431 on the periphery of pattern drum 122 engages and raises a thrust rod 432 out of engagement with the periphery of the main pattern drum 122 as the thrust rod 425 drops off of the cam 430 (Figure 32). The thrust rod 432 has an arm 433 on the upper end thereof (Figure 15) which extends forwardly and has a control element 434 thereon which, upon upward movement of thrust rod 432 and arm 433, opens the clamp and cutter mechanism to permit the elastic yarn R to be fed to the corresponding needles. Of course, as the lower end of thrust rod 432 (Figure 31) subsequently drops off of cam 431, it is apparent that the control element 434 then moves the clamp and cutter to closed position for cutting the elastic yarn and for clamping the portion of the yarn extending from the feeding end of the yarn feed finger 407.

The inelastic yarns Y extend from the corresponding disk type tension devices 405 to a suitable yarn tension and take-up mechanism 440 for each of said inelastic yarns Y. The yarn tension and take-up mechanisms are supported on a frame 441 suitably secured to one side of

a vertically disposed pattern bar guide 442 (Figures 1, 2, 3, 6 to 13 and 21 to 23, inclusive) which will be later described in detail.

The inelastic yarns Y extend downwardly and forwardly from the yarn tensioning and take-up devices 440 and pass through a suitable yarn guide 445 (Figures 15 and 16) which is suitably secured to a guide post 446 mounted for vertical sliding movement in a guide block 447 suitably secured to the upper surface of the circular bed plate 114 (Figures 16, 17 and 20). A plurality of superposed bell-crank-shaped yarn feed fingers 450 are pivotally mounted for movement about a substantially vertical axis on the upper end of the guide post 446, as best shown in Figures 15, 16 and 17, and each of the yarns Y, upon passing through the yarn guide 445, extends through the eye of a corresponding one of the yarn feed fingers 450.

Each yarn feed finger 450 has an outwardly projecting tail 451 thereon to which one end of a corresponding tension spring 452 is connected for normally urging the corresponding yarn feed finger 450 to inoperative position. The other or rear ends of the tension springs 452 are connected to a substantially L-shaped spring support bracket 453, the horizontal portion of which extends forwardly and is suitably secured to the guide post 446 (Figures 8, 15 and 17). The yarn feed fingers 450 are selectively raised and lowered according to predetermined pattern to selectively position the yarn feed fingers 450 on the same level as a yarn feed opening 454 (Figures 16 and 52) in the lower portion in the latch ring 113 so that, when the corresponding yarn feed finger 450 is swung inwardly by an arcuate yarn finger actuator 455, it directs the corresponding yarn Y through the opening 454 and to the needles in the usual manner or as is conventional on the Crawford Model AA machines.

The raising and lowering of the yarn feed fingers 450 and the swinging of the yarn finger actuator 455 is controlled by the improved lower auxiliary pattern drum 230. It will be noted in Figures 15 and 16 that the yarn finger actuator 455 is pivoted on the guide block 447 immediately adjacent the pivot point of the yarn feed fingers 450, as at 456. The means for raising and lowering the yarn feed fingers 450 and for actuating the yarn finger actuator 455 will be later described, since they are peculiar to the present invention. It will be observed in Figures 15 and 16 that a conventional inelastic yarn cutter mechanism generally designated at 460 is mounted above the sinker head 110 and immediately below the latch ring 113.

The inner ends of a plurality of inelastic yarn clamping devices, generally designated at 461, are selectively moved into position closely adjacent the yarn cutting mechanism 460 for clamping the corresponding yarn upon being cut and which corresponding yarn extends from a corresponding yarn feed finger 450. The yarn clamping devices 461 are substantially as shown on page 21 of said catalogue and the yarn cutting device 460 is shown on page 3 of said catalogue. Accordingly, only so much of the yarn cutting and clamping devices 460, 461 will be described as is necessary to understand the present invention.

Each of the yarn clamping devices 461 is mounted on the inner end of a bar 462 (Figures 14, 15, 16 and 18) and all of the bars 462 are guided for substantially horizontal inward and outward movement in a guide block 463 or clamp carriage 463 which is, in turn, mounted for vertical sliding movement on a post 464 carried by the circular bed plate 114. Each clamping device 461 is normally urged outwardly to inoperative position, along with its corresponding bar 462, by a tension spring 465. Since it is necessary that the clamping devices 461 are selectively positioned at the proper level prior to being moved inwardly to operative position, the guide block 463 (Figures 14, 15, 16, 17, 18 and 20) has a toothed member 466 thereon which is adapted to, at times, be

engaged by a mating toothed member, 467 preferably having a single tooth thereon, which is adapted to engage any one of the teeth in the first toothed member 466 upon the vertically movable carriage or guide block 463 being released, as will be later described.

It will be observed in Figure 18 that the carriage or guide block 463, when in lowered position, normally rests upon an abutment 470 carried by a conventional clamp positioning arm bracket 471. It will be observed in Figure 8 that the lower front portion of bracket 471 is suitably secured to or integral with the guide post 464 and its rear portion is disposed outwardly of the bed plate 114 and has a vertically disposed shaft 473 journaled therein (Figures 15, 20 and 21), to the reduced upper end of which a clamp positioning arm 474 is suitably secured, and to the lower end of which a crank 475 is suitably secured.

The clamp positioning arm 474 extends forwardly and is adapted to engage any one of the clamp bars 462, since the clamp bars 462, and guide block 463 are selectively raised and lowered by means to be later described. As each of the clamp bars 462 is moved inwardly to operative position between the latch ring 113 and the sinker head 110 it is necessary that the movable part or blade 461a (Figure 16) of the corresponding clamping device 461 and that the movable part or blade 460a of the cutter device 460 be moved to opened position to release the end of the corresponding yarn Y as it is directed through the yarn feed opening 454 (Figures 16 and 52) by the corresponding yarn feed finger 450.

On the other hand, upon subsequent withdrawal of the corresponding yarn feed finger 450 from operative position, it is necessary that the movable element 461a on the corresponding yarn clamping device 461 return to closed position, to which it is normally biased in a conventional manner, for clamping the corresponding yarn and it is also necessary that the movable blade or element 460a of the cutting device, which movable element is also normally biased to closed position, be permitted to move to closed position for cutting the corresponding yarn Y. To this end, a conventional clamp and cutter actuating plunger 480, which is normally biased upwardly to inoperative position by a tension spring 481 (Figures 14 and 18), is moved downwardly against the tails of the movable elements 460a, 461a by a pivoted cam or dog 482 (Figures 8, 14 and 18) which is pivoted, as at 483, on the upper portion of the guide post 464. It will be noted that the upper portion of the guide post 464 is off-set to accommodate the clamp and cutter actuating plunger 480 which is mounted for vertical sliding movement in the off-set upper portion of the guide post 464.

The cam 482 has the upper front end of a link 485 pivotally connected thereto which is normally urged forwardly and upwardly by a tension spring 486 (Figure 18) so the cam 482 is normally urged upwardly rather than toward the clamp and cutter actuating plunger 480. The connecting rod 485 is controlled by the improved lower auxiliary pattern drum 230 in a manner to be later described and it is thus seen that, with rearward and downward movement of the connecting rod or link 485, the clamp actuating plunger 480 is moved downwardly to engage the tails of and open the movable parts 460a, 461a of the cutting device 460 and the corresponding clamping device 461.

Narrowing picks

The narrowing picks 266, 267 (Figures 20 and 52) are of the variable capacity type well-known to those familiar with the Crawford Model AA machines and are shown in detail on page 17 of said catalogue. Since the capacity of narrowing picks 266, 267 is varied by respective cams 490, 491 on the main pattern drum 122 (Figures 26 and 33) in a conventional manner to cause the narrowing picks 266, 267 to, at times, pick up two needles out of action and, at other times, to pick up a

single needle out of action with each movement of the needle cylinder in the corresponding direction, a detailed description of the variable capacity narrowing picks 266, 267 will not be given, it being deemed sufficient to state that the medial portions of the narrowing pick structures are universally mounted on respective blocks 492, 492' fixed on the circular bed plate 114 (Figure 20). Also, opposite ends of an extensible link or composite link 493 are pivotally connected, by slot and pin connections, as 494, to the narrowing pick structures, rearwardly of the vertical axes thereof.

The effective length of the composite link 493 is varied in a conventional manner by a cam 495 (Figure 27) on the main pattern drum 122. Accordingly, a further description of the composite link 493 and the intervening connections extending therefrom to the main pattern drum 122 is deemed unnecessary, (see Figures 15, 17 and 20). It might be stated, however, that the length of the composite link 493 is relatively greater when narrowing one needle with each movement of the needle cylinder in each direction than it is when narrowing two needles with each movement of the needle cylinder in each direction.

As is well known in the art, it occasionally becomes necessary to swing the right-hand narrowing pick 266 inwardly to inoperative position during reciprocatory knitting so the first of leading needles in the course of a counterclockwise movement of the needle cylinder will not be elevated by the right-hand narrowing pick 266. In other words, it is necessary that the right-hand pick 266 be moved inwardly and upwardly to inoperative position in advance of the leading needles reaching the same in the course of a counterclockwise movement of the needle cylinder so that these leading needles will pass through the stitch cams.

Although means for moving the narrowing pick to inoperative position has been employed heretofore, it differs somewhat in the present application, since the latter means is controlled by the improved lower auxiliary pattern drum 230. Accordingly, it will be observed in Figure 20 that a right-hand narrowing pick de-activating member 3-e is fixed to the narrowing pick structure inwardly and rearwardly of the pivot point of the right-hand narrowing pick structure below the corresponding end of the composite link 493. This de-activating element 3-e extends rearwardly and is pivotally connected to the front end of a link 3-d so that, upon rearward movement of the link 3-d, the de-activating element 3-e moves the right-hand narrowing pick in a clockwise direction (Figure 20) to inoperative position. It will be observed in Figure 21 that the link 3-d extends rearwardly and is pivotally connected, as at 500, to a crank 3-c fixed on the upper end of the control rod 3.

It is apparent that, upon each succeeding cam 3-b (Figure 39) momentarily engaging the follower arm or lever 3-a, the de-activating element 3-e and pick 266 (Figure 20) are moved rearwardly to the inoperative position shown in Figure 20. However, as each successive cam 3-b (Figure 39) moves out of engagement with the cam follower or control finger 3-a, it is apparent that, since the connecting rod or link 3-d loosely penetrates pivot pin 500 (Figure 21), the right-hand narrowing pick 266 is free to swing inwardly and outwardly in the usual manner.

The parts of the machine heretofore described, with the exception of the narrowing pick de-activating element 3-e and its controls, and with the exception of other parts referred to as being parts of the present invention, are conventional and it is with such parts that the present invention is particularly adapted to be associated, although it is to be distinctly understood that the principles of the present invention may be readily applied to other types of circular knitting machines.

The present machine also includes a latch opener 502, which operates in a conventional manner, but which, as

shown in Figures 14 and 15, is mounted and controlled in a manner peculiar to the present machine so it is moved to inoperative position relative to the needles N whenever the inwardly biased second needle lowering switch cam $8-e$ (Figures 18 and 52) is withdrawn from operative position. At times, the latch opener 502 and the second needle lowering switch cam $8-e$ are caused to move to inoperative position by the cams $8-b$ on the improved lower auxiliary pattern drum 230 (Figure 44) and, at other times, the latch opener 502 and the second needle lowering switch cam $8-e$ are moved to inoperative position by the cams 503 on the main pattern drum 122 (Figure 24).

Referring to Figures 14 and 15, it will be observed that the latch opener 502 is in the form of an elongated rod whose hooked-shaped inner end is disposed between the proximal surfaces of the latch ring 113 and the sinker head 110 and the medial portion of the latch opener 502 is eccentrically secured in a block 505 , as at 506 , on a stationary arm 507 . The arm or bracket 507 is fixed on the upper end of a post 510 . The lower end of post 510 is suitably secured to the outer surface of the circular bed plate 114 . The block 505 and latch opener 502 are normally urged in a counterclockwise direction in Figure 15 by a spring 511 and such movement is limited by an abutment 512 on block 505 engaging an adjustable stop 513 suitably secured to the arm 507 .

The tail or outer end of the latch opener 502 is engaged by the upper portion of a rod 515 whose lower end is suitably secured to the medial portion of a crank 516 (Figures 14, 15 and 18) fixed to and projecting outwardly from a substantially vertically disposed rocker shaft 520 journaled in a bearing block 521 suitably secured to the front surface of the circular bed plate 114 . The upper end of shaft 520 also has a crank 522 fixed thereon whose free inner end in Figure 14 is disposed between the block 286 and an abutment 523 on the outer end of the stem of the second needle lowering switch cam $8-e$.

The outer end of crank 516 has the front ends of a pair of links $8-d$, 525 pivotally connected thereto (Figures 8, 14, 15, 18 and 20) and it will be observed in Figures 8, 10, 18 and 24 that the rear end of link 525 is pivotally connected to the substantially vertical arm of a bell crank 527 oscillatably mounted, as at 530 (Figure 18), on a fixed part of the machine frame. The other arm of bell crank 527 normally rests upon a lateral projection or pin 531 carried by a thrust rod 532 guided for vertical movement in the guides 426 , 427 . At times, the lower end of thrust rod 532 bears against the periphery of the main pattern drum 122 and, at other times, it is engaged by corresponding cams 503 (Figures 18 and 24).

It will be observed in Figures 8, 9 and 18 that the rear end of link $8-d$ is pivotally connected to the free end of a crank $8-c$ fixed to the upper portion of control rod 8 immediately below the control rod guide 222 . It is apparent that when the follower arm $8-a$ (Figures 9 and 44) on the lower end of control rod 8 is in engagement with the periphery of the improved lower auxiliary pattern drum 230 , the latch opener 502 and the second needle lowering switch cam $8-e$ may be moved outwardly to inoperative position upon anyone of the cams 503 (Figure 24) moving into engagement with the thrust rod 532 . Of course, upon the thrust rod 532 dropping off of any one of the cams 503 , the latch opener 502 and the second needle lowering switch cam $8-e$ will return to operative position. On the other hand, when the follower arm $8-a$ (Figures 9 and 44) is engaged by any one of the cams $8-b$ on the lower auxiliary pattern drum 230 , it is apparent that this will also move the latch opener 502 and the second needle lowering switch cam $8-e$ to inoperative position.

The widening pick slide cams 292 , $292'$ are controlled solely by the main pattern drum 122 and a cam 535 thereon (Figure 25) although it is apparent that the widening pick slide cams 292 , $292'$ may also be controlled

by suitable cams on the improved lower auxiliary pattern drum 230 , if desired, since the intervening connections between the slide cams 292 , $292'$ and the main pattern drum 122 are similar to those between the second needle lowering switch cam $8-e$ and the main pattern drum 122 in Figures 18 and 24.

It will be observed in Figure 20 that the slide cams 292 , $292'$ are normally urged outwardly by respective tension springs 536 , $536'$ and the rear ends of links 537 , $537'$ are pivotally connected to the medial portion of the respective slide cams 292 , $292'$. The links 537 , $537'$ converge forwardly in Figure 20 and are pivotally connected to the upper ends of respective cranks 540 , $540'$ (Figures 8, 14, 15 and 20). The lower ends of the cranks 540 , $540'$ are fixed on opposite ends of a shaft 541 journaled in bearing blocks 542 projecting forwardly from the front portion of the circular bed plate 114 . The left-hand end of shaft 541 in Figures 14, 15 and 20 has a crank 543 fixed thereon to the lower end of which the front end of a link 544 is pivotally connected. The link 544 extends rearwardly in Figures 8 and 18 and is pivotally connected to one arm of a bell crank 545 pivotally mounted on the pivot 530 heretofore described (Figures 10 and 18).

The other arm of bell crank 545 normally bears against the upper edge of an abutment 547 which extends inwardly and is suitably secured to the medial portion of a thrust rod 548 (Figures 10 and 25). The thrust rod 548 is also mounted for vertical movement in the guides 426 , 427 and the lower end of thrust rod 548 rests against the periphery of the main pattern drum 122 or the cam 535 as the case may be. It is apparent that, with engagement of the lower end of thrust rod 548 (Figure 25) by the periphery of pattern drum 122 and cam 535 , in alternation, the slide cams 292 , $292'$ are shifted longitudinally relative to the guide plates 291 , $291'$ for correspondingly activating and de-activating the widening picks 252 , 253 , 271 , 272 .

Brake for shogging clutch

The Crawford model AA machine has a pattern controlled brake mechanism thereon for preventing inadvertent rotation of the needle cylinder during each shogging operation and the brake mechanism in the present case differs primarily from the conventional brake mechanism in the manner in which it is controlled, since the brake mechanism in the present instance is controlled by the improved lower auxiliary pattern drum 230 . Referring to Figures 8, 11 and 12, the brake mechanism comprises a brake drum 551 which is substantially encircled by a pliable brake band 552 provided with a suitable friction liner 553 on the inner surface thereof. The brake drum 551 is suitably secured to the outer surface of the gear 187 and the shaft 153 extends through the central portion of the brake drum 551 as best shown in Figure 12.

It will be observed in Figure 8 that one end of the brake band 552 is pivotally connected, as at 555 , to a bracket 556 (Figures 8 and 11) depending from the circular bed plate 114 . The other end of the brake band 552 is pivotally connected to the lower end of a lever 557 oscillatably mounted intermediate its ends on the bracket 556 . The upper end of lever 557 has the front end of a link $1-d$ pivotally connected thereto whose rear end (Figure 9) is pivotally connected to a crank $1-c$ fixed on the control rod 1 immediately below the upper control rod guide 222 .

It will be observed in Figures 37 and 38 that the cams $1-b$, $2-b$ are correspondingly arranged on the improved lower auxiliary pattern drum 230 and it is apparent, therefore, that engagement of follower arm $1-a$ by any one of the cams $1-b$ occurs simultaneously with engagement of the follower arm $2-a$ by a corresponding one of the cams $2-b$. Accordingly, since the link $2-d$ is connected to the crank $2-c$ (Figures 9 and 12), whenever the follower arm or finger $2-a$ is engaged by one of the cams $2-b$ (Figure 38), the plunger 211 is moved inwardly

In Figure 12 to move the locking finger 204 out of engagement with a corresponding notch 203 in the locking disk 201.

At this time, it is apparent that, upon engagement of the follower finger or arm 1-a by any one of the cams 1-b (Figure 37), the link 1-d moves rearwardly in Figure 8 to impart counterclockwise movement to lever 557 and to thereby actuate the brake band 552, thus preventing inadvertent rotation of the gear 187 and the needle cylinder 106 during rotation of the shogging disk or wheel 200 relative to the disk 201 (Figure 12). It is apparent that movement of corresponding cams 1-b, 2-b out of engagement with control fingers 1-a, 2-a permits the plunger 211 to return to the position shown in Figure 12, under pressure of the spring 214, and releases the brake band 552.

It has already been described how the first row of cams 1-b (Figure 37) on the improved pattern drum 230 controls the clutch brake band 552 (Figure 8); how the second row of cams 2-b (Figure 38) controls the clutch plunger 211 (Figure 12); how the row of cams 3-b (Figure 39) controls the narrowing pick de-activating elements 3-e (Figure 20); and how the row of cams 8-b (Figure 44) on the lower auxiliary pattern drum 230 controls the second needle lowering switch cam 8-e and the latch opener 502. The connections between the lower auxiliary pattern drum 230 and the inelastic yarn feeding, clamping and cutting means will now be described.

The cams 4-b (Figure 40) control the yarn finger actuator 455 (Figures 15 and 16). To this end, it will be observed in Figures 8, 9 and 21 that the upper end of the control rod 4 has a crank 4-c fixed thereon to whose free end the rear end of a link 4-d is pivotally connected. It will be observed in Figures 15 and 16 that the front end of link 4-d is connected to the yarn feed actuating arm 455 and the link 4-d is normally urged forwardly, to thereby normally urge the yarn feed actuating arm 455 in a clockwise direction in Figure 16 (to inoperative position), by a tension spring 560 (Figure 21). The rear end of the spring 560 is connected to the medial portion of the link 4-d and the front end thereof is connected to a fixed part of the knitting machine.

It is apparent that, as each successive cam 4-b (Figure 40) moves into engagement with the control finger or follower arm 4-a, this imparts rearward movement to the link 4-d (Figure 21) in a step-by-step manner so the free end of the yarn feed actuator 455 (Figures 15 and 16) will engage the tail 451 of the yarn feed finger 450 disposed on the corresponding level to move the same inwardly in a stepped manner for threading the corresponding yarn Y through an angular slot 454a into the yarn feed opening 454 (Figures 16 and 52) and to thereby feed the latter yarn to the needles. The yarn is threaded into the opening 454 in a conventional manner and a detailed description thereof is deemed unnecessary.

It will be noted that the cams 5-b (Figure 41) on the improved lower auxiliary pattern drum 230 are of varying heights or thicknesses, since these cams function, in a manner to be presently described, to raise the yarn feed fingers 450 to predetermined levels so the yarn feed fingers 450 are selectively positioned to be subsequently engaged by the yarn finger actuating arm 455 in the manner heretofore described. Referring to Figures 8, 9 and 21, it will be observed that the upper end of the control rod 5 has a crank 5-c fixed thereon to whose free end the rear end of a connecting rod or link 5-d is pivotally connected.

The front end of link 5-d is pivotally connected to a substantially vertical arm of a bell crank 561 oscillatably mounted on a shaft 562 (Figures 8, 9, 15, 17, 18, 20 and 21). The shaft 562 is journaled in bearings 563, one each suitably secured to the arms 224, 225 of the arcuate control rod guide 222 as best shown in Figure 21. The other arm of bell crank 561 has a follower or roller 564 on the front end thereof which bears against the lower surface of a cam-like projection 565 (Figure 17) suitably

secured to, or integral with, the horizontal leg of the substantially L-shaped spring support 453 heretofore described. Since the spring support 453 is fixed to the guide post 446 it is apparent that the uppermost yarn feed finger 450 is disposed in alignment with the yarn feed finger actuator 455 when the control finger 5-a (Figure 41) is in engagement with the periphery of the improved lower auxiliary pattern drum 230. It is also apparent that, as the various cams 5-b engage the control finger 5-a, corresponding movement is imparted to the bell crank 561 to raise or lower the yarn feed fingers 450, as the case may be, to correspondingly position selected yarn feed fingers 450 on the operating level.

Referring to Figure 42, the cam 6-b on the lower auxiliary pattern drum 230 is used for moving the toothed member 467 (Figure 18) out of engagement with the toothed member 466 so the clamp carriage 463, if in raised position, may move downwardly against the stop 470. To this end, it will be observed in Figures 8, 9 and 18 that the upper portion of control rod 6 has a crank 6-c fixed thereon, immediately below the upper control rod guide 222, to which the rear end of a link 6-d is pivotally connected. The link 6-d extends forwardly and its front end (Figures 8 and 18) is pivotally connected to the lower end of the toothed member 467, which toothed member is in the form of a lever oscillatably mounted intermediate its ends, as at 570 (Figure 18), on the circular bed plate 114.

A spring 571 is connected at its front end to the lower portion of the toothed member 467 and its rear end is connected to the arm 223 of the arcuate control rod guide 222 so the toothed member 467 is normally urged against the mating toothed member 466 as shown in Figure 18. It is apparent that, upon movement of cam 6-b (Figure 42) into engagement with control finger or follower arm 6-a, the free end of the upper crank 6-c on the control rod 6 moves forwardly, thereby moving the toothed member 467 in a counterclockwise direction in Figure 18, out of engagement with the mating toothed member 466.

The cams 7-b (Figure 43) on the improved lower auxiliary pattern drum 230 control a cam 482 (Figure 8) to effect the opening and closing of the clamping and cutting devices 460, 461. To this end, it will be observed in Figures 8, 9, 15 and 21 that the upper end of the control rod 7 has a crank 7-c fixed thereon, to the free end of which the rear end of a link 7-d is pivotally connected. The front end of link 7-d is pivotally connected to one arm of a bell crank 575 oscillatably mounted on a shaft 576 (Figures 15, 18 and 21). The shaft 576 is fixed in a block or projection 577 suitably secured to, or integral with, the arcuate upper control rod guide 222. The other arm of said bell crank 575 has the lower rear end of the link 485 pivotally connected thereto.

It is thus seen that, when the control finger 7-a (Figures 9 and 43) is in engagement with the periphery of the improved lower auxiliary pattern drum 230, the plunger 480 (Figures 8, 15 and 18) remains in elevated position and, upon any one of the cams 7-b engaging the control finger 7-a, the bell crank 575 is then rotated in a counterclockwise direction in Figure 18 to cause the cam 482 to move downwardly in engagement with the plunger 480 to thereby open the normally closed clamp and cutter movable elements 460a, 461a of the cutter device 460 and clamp device 461.

It will be observed in Figure 45 that the cams 9-b on the lower auxiliary pattern drum 230 are stepped and are also of varying height, since these cams are used for selectively raising the yarn clamping devices 461 to operating level, according to a predetermined pattern. It will be noted in Figures 41 and 45 that the cams 5-b are positioned to correspond to the respective cams 9-b since the clamping devices 461 must be raised and lowered in unison with the yarn feed fingers 450.

It will be observed in Figures 8, 9 and 21 that the upper end of the control rod 9 has a crank 9-c fixed

thereon to the free end of which a link 9-d is pivotally connected. The front end of link 9-d is pivotally connected to the upper end of a crank 580 whose lower end is fixed on the shaft 562 (Figures 18 and 21). The left-hand end of the shaft 562 (Figure 21) has a crank 581 fixed thereon which extends forwardly and engages the lower surface of a roller 582 (Figures 15, 18, 20 and 21) mounted on the guide block or carriage 463. It is thus seen that the cams 9-b move the clamping devices upwardly varying distances, whereupon the toothed members 466, 467 prevent downward movement of the carriage or guide block 463 as each successive cam 9-b moves out of engagement with the control finger 9-a (Figure 45), except when the cam 6-b (Figure 42) engages the control finger 6-a to move the toothed member 467 out of engagement with the mating toothed member 466, in the manner heretofore described.

It is apparent that the highest points of the cams 9-b in Figure 45 are so arranged as to raise the carriage or guide block 463 to where the corresponding clamping devices 461 are disposed slightly above optimum operating level, whereupon the said high surfaces of the cams 9-b move out of engagement with the follower arm or control finger 9-a to permit the carriage 463 to drop slightly to insure that the mating toothed members 466, 467 are in proper interengagement. Now, when the carriage or guide block 463 has been moved to the desired level in the manner last described, the corresponding clamp arm 462 is engaged and swung inwardly by the clamp positioning arm 474 to move the corresponding clamping device 461 into operative position as shown in Figure 16.

To this end, the arm or crank 475 on the lower end of shaft 473 has the front end of a link 10-d pivotally connected thereto whose rear end is pivotally connected to the outer end of a crank 10-c (Figures 8 and 21). The inner end of crank 10-c is fixed to the upper end of control rod 10 and the free end of the clamp positioning arm 474 is normally urged outwardly by a tension spring 585. It will be noted that the notches defined between adjacent cams 10-b (Figure 46) on the improved auxiliary pattern drum 230 coincide with the cams 9-b in Figure 45 and the cam 6-b in Figure 42. Accordingly, during the lowering or raising of the clamp carriage or guide block 463 in Figures 14 and 18, as effected by the respective cams 6-b, 9-b, it is apparent that the control finger 10-a is then in engagement with the periphery of the lower auxiliary pattern drum 230 and the clamp positioning finger 474 is then positioned outwardly of the vertical plane of the outer ends of the clamp arms 462.

However, after the clamp carriage or guide block 463 is positioned at the desired predetermined level, a corresponding cam 10-b (Figure 46) engages the control finger 10-a to move the same in a counterclockwise position which will, of course, also impart movement to the crank 10-c in a counterclockwise direction in Figure 21 to thereby impart corresponding movement to the clamp position arm 474 through the intervening connections. Accordingly, the clamp positioning arm 474 moves inwardly to occupy the position shown in Figures 16 and 21 to thereby move the corresponding yarn clamping device 461 into operative position. Thereafter, the clamp and cutter opening plunger 480 moves downwardly, in the manner heretofore described, to move the movable parts 460a, 461a of the cutter device 460 and the clamping device 461 to open position for releasing the corresponding yarn Y from the clamping device 461 as the corresponding yarn feed finger 450 directs the yarn through the yarn feed opening 454 (Figures 16 and 52) to the needles N.

Referring to Figures 15, 20, 21 and 52, the first needle lowering switch cam 11-e is controlled by the improved lower auxiliary pattern drum 230. However, the needle

cams 12-e, 13-e, 14-e are at times, controlled by the improved lower auxiliary pattern drum 230 and, at other times, they are controlled by the main pattern drum 122. Of course, the right-hand widening pick feed cam 13-e is also controlled by the feed cam actuating arm 251 during oscillation thereof as imparted thereto by the cams 320, 320' in the racking drum 317, at predetermined intervals, in the manner heretofore described.

As heretofore described, the first needle lowering switch cam 11-e and the second elevating switch cam 12-e are mounted in the block 285 and are normally spring-biased outwardly. It will be observed in Figures 15, 20 and 21 that the outer ends of the stems of the needle cams 11-e, 12-e are engaged by corresponding arms of respective bell cranks 586, 587 which are oscillately mounted on a common stud or pivot pin 590 suitably secured to the circular bed plate 114. The front ends of the links or connecting rods 11-d, 12-d are pivotally connected to the other arms of the respective bell cranks 586, 587.

It will be observed in Figures 9 and 21 that the rear ends of the links 11-d, 12-d are pivotally connected to the free ends of respective cranks 11-c, 12-c fixed on the upper ends of the respective control rods 11, 12. It is apparent, by referring to Figures 47 and 48 that the needle cams 11-e, 12-e occupy withdrawn or inoperative position when the control fingers or follower arms 11-a, 12-a are in engagement with the periphery of the lower auxiliary pattern drum 230 and, upon any one of the respective cams 11-b, 12-b engaging the respective control fingers 11-a, 12-a, it is apparent that the control rods 11, 12 move in a counterclockwise direction in Figures 21, 47 and 48 to thereby move the bell cranks 586, 587 in a clockwise direction and to thereby move the respective needle cams 11-e, 12-e into operative position, according to a predetermined pattern.

As heretofore stated, the stems of the right-hand widening pick feed cam 13-e and the first elevating switch cam 14-e (Figures 20 and 52) are mounted for radial movement in the common block 281 and are normally biased outwardly to inoperative position. It will be observed in Figures 14 and 20 that the outer ends of the stems of the respective needle cams 13-e, 14-e are engaged by corresponding ends of control levers 591, 592. The control levers 591, 592 are oscillately mounted intermediate their ends on a common post 593 whose lower end is suitably secured to a bracket 594 fixed to the front of the circular bed plate 114.

The outer ends of the control levers 591, 592 have the front ends of respective links 13-d, 14-d pivotally connected thereto whose rear ends are pivotally connected to the free ends of cranks 13-c, 14-c fixed on the upper ends of the respective control rods 13, 14 (Figure 9). A tension spring 595 (Figure 21) may be provided to assist in urging the control lever 592 to inoperative position or outwardly with respect to the corresponding needle cam 14-e. It is thus seen that, when the follower arms or control fingers 13-a, 14-a are in engagement with the periphery of the improved lower auxiliary pattern drum 230 (Figures 49 and 50) the respective needle cams 13-e, 14-e (Figures 20 and 52) may occupy inoperative or withdrawn position. However, upon any one of the corresponding cams 13-b, 14-b engaging the respective control fingers 13-a, 14-a this imparts counterclockwise movement to the cranks 13-c, 14-c in Figure 21 to thereby impart clockwise movement to the respective control levers 591, 592 in Figures 15, 20 and 21 to thereby move the respective needle cams 13-e, 14-e into operative position at predetermined intervals according to a predetermined pattern.

As heretofore stated the needle cams 12-e, 13-e, 14-e are also controlled, at times, by the main pattern drum 122. To this end, it will be observed in Figure 9 that the medial portions of the control rods 12, 13, 14 have respective cranks 12-f, 13-f, 14-f fixed thereon, to the free

ends of which the rear ends of respective links 12-g, 13-g, 14-g are pivotally connected. The front ends of links 12-g, 13-g, 14-g are pivotally connected to the lower ends of substantially vertical arms of respective bell cranks 600, 601, 602 (Figures 8, 15, 17, 20, 28, 29 and 30). It will be observed in Figures 15 and 20 that the bell cranks 600, 601, 602 are oscillatably mounted on a shaft 603 projecting from the left-hand end of the bracket 422 heretofore described.

The upper substantially horizontal arms of the bell cranks 600, 601, 602 normally bear against the upper ends of respective thrust rods 605, 606, 607 (Figures 30, 29 and 28, respectively) which are guided for vertical movement in the guides 426, 427 and whose lower ends are engaged by the periphery of the main pattern drum 122 or are engaged by respective cams 610, 611, 612, arranged according to a predetermined pattern.

It is thus seen that, when the lower ends of the thrust rods 605, 606, 607 are in engagement with the periphery of the main pattern drum 122 the respective needle cams 12-e, 13-e, 14-e occupy inoperative position or they may be moved into operative position, since the horizontal arms of the respective bell cranks 600, 601, 602 may be moved upwardly out of engagement with the upper ends of the respective thrust rods 605, 606, 607 upon engagement of the follower arms or control fingers 12-a, 13-a, 14-a by the respective cams 12-b, 13-b, 14-b on the improved lower auxiliary pattern drum 230.

However, when the cams 12-b, 13-b, 14-b are not aligned with the respective follower arms or control fingers 12-a, 13-a, 14-a, it is apparent that if the thrust rods 605, 606, 607 (Figures 30, 29 and 28, respectively) are then engaged by any one of the corresponding cams 610, 611, 612, the respective bell cranks 600, 601, 602 are moved in a counterclockwise direction in Figures 8, 17, 28, 29 and 30 thereby causing the free ends of the cranks 12-f, 13-f, 14-f to move away from the observer in Figure 9. It is apparent that this will impart counterclockwise movement to the cranks 12-c, 13-c, 14-c in Figure 21 to thereby move the needle cams 12-e, 13-e, 14-e into operative position through the intervening connections heretofore described, also, according to a predetermined pattern.

This completes the description of the intervening connections between the lower improved auxiliary pattern drum 230 and the various parts controlled thereby.

The welt needle lowering cam 254 (Figures 20 and 52) and the special sinker cam 275 are not controlled by the improved lower auxiliary pattern drum 230. However, they are controlled by main pattern drum 122 in a manner differing substantially from the manner in which these cams are controlled on the conventional Crawford machines, as will now be described in detail. It will be observed in Figures 14 and 16 that the special sinker cam 275 has a stem 275a thereon to the outer end of which a tension spring 620 is connected and the inner end of the spring 620 is connected to the sinker head 110. Thus, the tension spring 620 normally urges the special sinker cam 275 (Figures 14, 15 and 16) inwardly toward the center of the needle cylinder, to inoperative position.

The hooked outer end of the stem 275a is engaged by a pivoted latch or dog 621 pivotally mounted on the upper end of a bracket 622 (Figures 14, 15 and 16) which is fixed to the upper surface of the block 282 in which the stem of the welt needle lowering cam 254 is mounted for radial sliding movement. The outer end of the stem of the welt needle lowering cam 254 in Figures 16 and 20 also has a bracket 625 fixed thereon which projects upwardly above the level of the lower portion of the pivoted dog 621 as shown in Figure 14.

One arm of a bell crank 627 is pivotally connected to the outer end of the stem of the welt needle lowering cam 254 and the other arm of said bell crank 627 has the front end of a connecting rod or link 630 pivotally connected thereto. The bell crank 627 is oscillatably

mounted, as at 631, on the side deck 105c of the upper cast frame 105. The rear end of link 630 (Figures 15 and 20) is pivotally connected to one end of a control lever 633 oscillatably mounted, as at 634, on the lower horizontal portion of the bracket 422 heretofore described.

The other end of the control lever 633 is normally urged against the rear surface of a thrust rod 636 (Figures 20 and 34), since the welt needle lowering cam 254 is normally spring-biased outwardly in a conventional manner as heretofore described. The thrust rod 636 has a cam element 637 on the upper end thereof (Figure 34) which is inclined at its upper end so that upward movement of the thrust rod 636 imparts rearward movement to the corresponding end of control lever 633. It is apparent, by referring to Figures 15 and 20, that rearward movement of said end of the control lever 633 will impart clockwise movement to the bell crank 627 to thereby move the welt needle lowering cam 254 into operative position.

Referring again to Figure 34, it will be observed that the thrust rod 636 is guided in the guides 426, 427 heretofore described and the lower end of the thrust rod 636 engages either the periphery of the main pattern drum 122 or a cam 640 fixed thereon. It is apparent that, upon cam 640 moving into engagement with the lower end of the thrust rod 636, it is moved upwardly to move the welt needle lowering cam 254 into operative position in the manner heretofore described. As the cam 254 is moved into operative position, the bracket 625 on the stem thereof engages the lower portion of the dog 621 (Figure 14) to thereby impart clockwise movement thereto. Accordingly, the upper portion of the dog 621 will then impart outward movement to the special sinker control cam 275 to move the same into operative position for withdrawing the sinkers at the point at which the elastic yarn R is fed to the needles.

Improved pattern drum and pattern bar for controlling same

The various cams on the improved lower auxiliary pattern drum 230 and their function having been described, the manner in which the improved pattern drum is supported and driven will now be described. It will be best observed in Figures 6 and 7 that the improved pattern drum 230 is in the form of a relatively large cylindrical shell 650 having a plurality of vertically spaced peripheral ribs or projections 651 on the outer surface thereof which define grooves therebetween in which the various cams 1-b to 14-b are secured (Figures 37 to 50, inclusive). An annular ratchet ring or ratchet wheel 652 is fixed on the upper end of the cylindrical shell 650 with the outer edges of the teeth thereof being substantially flush with the outer periphery of the cylindrical shell 650.

The inner portion of the annular ratchet wheel 652 projects substantially beyond the inner surface of the shell 650 and serves as a race for supporting the pattern drum 230, since the lower surface of the inwardly projecting portion of the annular ratchet wheel 652 rests upon a plurality of supporting rollers 654 (Figure 51) and the inner edge of the annular ratchet wheel 652 rides in engagement with a plurality of guide rollers 655. The supporting rollers 654 and guide rollers 655 are provided in pairs and each pair of rollers 654, 655 is carried by a corresponding support bracket or block 656 suitably secured to the lower surface of the pattern drum supporting platform 173, as by screws 657. The blocks or brackets 656 are preferably circularly spaced and equidistant so the rollers 655 thereon maintain concentricity of the lower auxiliary pattern drum 230 throughout step-by-step rotation thereof.

It will be observed in Figure 51 that each supporting roller 654 is journaled on a shoulder screw 660 projecting outwardly from the corresponding block or bracket 656 and each roller 655 is journaled on a stud or shoulder

screw 661 suitably secured to the block 656 and being positioned in a notch 662 formed in the outer end of the block 656 so the upper edge of each roller 655 is disposed substantially on the same level as the main body portion of the block or bracket 656. In order to prevent inadvertent rotation or back-lash of the improved pattern drum 230, the platform 173 has a plurality of circularly spaced friction devices thereon each of which is broadly designated at 663 and which is shown in the form of an inverted cup-shaped housing suitably secured to the upper surface of the platform 173 and in which a friction element or plunger 665 is mounted for vertical sliding movement.

It will be observed in Figure 7 that the lower portion of each friction element 665 loosely penetrates the platform 173 and is urged against the upper surface of the annular ratchet wheel 652 by a compression spring 666. The pressure of the compression spring 666 is adjusted by an adjustment screw 667 threadably penetrating the upper end of the housing of each friction element or device 663. It will be observed in Figures 6 and 7 that the cylindrical shell 650 and the annular ratchet wheel 652 of the auxiliary pattern drum 230 encircle the frame of the knitting machine, particularly the legs 101 to 104 thereof, and the platform 173 has openings 670, 671, 672 therein. The front and rear reaches or runs of the pattern chain 163 loosely extend through the openings 670, 671 and the improved pattern bar, its guide support 442 and its rack, to be later described, extend through the opening 672.

Intermittent step-by-step rotation is imparted to the improved lower auxiliary pattern drum 230 by means of a ratchet pawl 675 which is, at times, reciprocated in engagement with the ratchet wheel 652 and which, at other times, remains stationary although it is still in engagement with the ratchet wheel 652 and, at still other times, the ratchet pawl 675 is reciprocated, but is held out of engagement with the ratchet wheel 652, all of these operations being controlled indirectly by the main pattern chain 163. As heretofore described, conventional means such as disclosed in said Patent No. 1,152,850 imparts a step in rotation to the pattern chain 163 and to the main pattern drum 122 with every fourth revolution of the needle cylinder 106.

It will be observed in Figure 11 that the right-hand end of the shaft 161 on which the ratchet wheel 162 is loosely mounted has a conventional speed-controlling pattern wheel or ratchet wheel 676 loosely mounted thereon adjacent the right-hand standard 105b of the upper cast frame 105. The outer face of the ratchet wheel or speed control pattern wheel 676 has a plurality of circularly spaced cams 677 thereon which are adapted to successively engage a dog 680 (Figures 2 and 3) depending from the belt shifter 141, at predetermined intervals, for shifting the belt 140 (Figure 12) from the high speed pulley 127 to the slow speed pulley 132 in a conventional manner.

Although the ratchet wheel 676 and cams 677 are conventional, the ratchet wheel 676 is driven in a manner peculiar to the present invention and the cams 677 thereon serve to determine intervals in which reciprocation is imparted to pawl 675 (Figures 3 and 6). A ratchet pawl 681 is normally urged downwardly (Figure 3) into engagement with the ratchet wheel 676 by a tension spring 682. The ratchet pawl 681 is also normally urged rearwardly by a tension spring 683.

The rear lower end of ratchet pawl 681 is pivotally connected to the lower end of a crank 684 (Figures 2, 3 and 9) whose upper end is fixed to or integral with a hub 685 (Figures 10 and 21) oscillatably mounted on a shaft 686. The shaft 686 is fixed in opposite forwardly and rearwardly extending arms of the substantially U-shaped bracket 322 and is also fixed in the upper end of the brace 325. The lower end of a crank 687 is also connected to the hub or tubular member

685 and the upper end thereof has a follower 690 (Figure 10) thereon which is, at times, permitted to engage either the cams 330 or the periphery of the racking drum 317, as the case may be, to rack the ratchet or cam wheel 676.

It is apparent that the spring 683 (Figure 3) normally urges the follower 690 (Figure 21) toward the periphery of the racking drum 317. However, the pawl 681 is prevented from moving rearwardly, at times, by a pattern controlled restraining latch 692 (Figure 3) engaging a projection 693 on the medial portion of the crank arm 684. The front end of the restraining latch 692 is fixed on one end of a shaft 694 (Figures 2, 3, 9 and 13) journaled in bearing blocks 695 suitably secured to the rear edges of the standards 105a, 105b of the upper cast frame 105.

The other end of shaft 694 has the front end of an arm or crank 696 fixed thereon (Figures 9, 10 and 13) which extends rearwardly and it then extends at substantially right angles and has the lower end of a link 697 pivotally connected thereto. The upper end of link 697 in Figures 8, 9, 10 and 21 is pivotally connected to the substantially horizontal arm of a substantially L-shaped control finger 700 pivotally mounted on a shaft or stud 701. The stud 701 is fixed in a block 702 suitably secured to the rear surface of one of a pair of gibs 703, 704 which serve to retain an improved intermediate pattern mechanism embodied in a vertically movable pattern bar or plate 705 in the grooved rear portion of the pattern bar guide 442.

It will be best observed in Figure 10 that the vertical pattern bar 705 has three longitudinally extending rows of vertically spaced holes 15, 16, 17 therein, in certain of which respective pattern pins or projections 15a, 16a, 17a are positioned in accordance with a predetermined pattern. A longitudinally extending rack 706 is also suitably secured to the rear surface of the pattern bar 705 between the rows of holes 16, 17.

The substantially vertical leg or the reading end of the L-shaped finger 700 is urged against the rear surface of the pattern bar or plate 705 by a tension spring 707 (Figure 10) whose lower end is connected to the medial portion of the link 697 and whose upper end is connected to a spring anchor bar 708 (Figures 10 and 13) suitably secured to the rear surface of the substantially L-shaped bracket 323 heretofore described. The reading end of the control finger 700 is disposed in vertical alignment with the row of holes 15 and the corresponding pattern pins 15a.

The pattern bar 705 is moved upwardly in a step-by-step manner under control of the pattern chain 163 in a manner to be later described. Thus, upon any one of the pattern pins 15a moving into engagement with the reading end of control finger 700, the control finger 700 is moved in a counterclockwise direction in Figure 8 to thereby impart downward movement to link 697 and crank 696 in Figures 8, 9, 10 and 13. It is apparent that this causes the latch 692 to move downwardly in Figures 2 and 3 to thus permit the spring 683 to move the pawl 681 rearwardly in an inactive stroke each time one of the cams 330 on the racking drum 317 moves out of engagement with the follower 690. It follows, therefore, that each succeeding cam 330 on the racking drum 317 will impart an active stroke to the pawl 681 until pattern bar 705 is again racked sufficiently to move the corresponding pin or pins 15a out of engagement with the control finger 700.

Referring to Figures 3 and 6, it will be observed that the ratchet pawl 675 is pivotally connected, as at 710, to a projection 711 on a pawl-carrying element or slide 712. The pawl-carrying slide 712 is guided for forward and rearward movement, on the upper surface of the platform 173, in spaced guide blocks 713, 714 suitably secured to the upper surface of platform 173. The pawl-carrying slide 712 is normally urged rearwardly by a

tension spring 715 whose front end is connected to the medial portion of slide 712 and whose rear end is connected to a spring anchor 716 suitably secured to the platform 173.

The rear end of the slide 712 has a pivot block 717 fixed thereon in which a pivot shaft 720 is loosely positioned. The pivot shaft 720 extends inwardly and is fixed to the lower end of the substantially vertical arm of a bell crank 721. The bell crank is oscillatably mounted at the junction of its arms, as at 722, on the outer side of the standard 105b of the upper cast frame 105. The other arm of said bell crank 721 has a follower 723 thereon (Figures 2, 3, 9 and 10) which is successively engaged by the circularly spaced racking cams 331 on the racking drum 317 whenever the bell crank 721 is free to move in a counterclockwise direction in Figure 3, since the cam follower 723 is normally urged toward the racking drum 317 by the spring 715 heretofore described (Figures 3 and 6). A tension spring 724 (Figure 3) also assists in urging the motion-transmitting lever or bell crank 721 in a counterclockwise direction.

The rearward movement of the slide 712 and corresponding counterclockwise movement of the bell crank 721 in Figure 3 is, at times, prevented by the cams 677 on the pattern wheel 676, which is the reason why step-by-step rotation of the pattern wheel 676 is controlled by the pattern bar 705 which is, in turn, controlled by the pattern chain 163. The means for restraining rearward movement of the slide 712 will now be described.

It will be observed in Figures 2, 3, 10 and 11 that a follower 730 is disposed in the circular plane or path of travel of the cams 677 on the ratchet or pattern wheel 676. The follower 730 is in the form of a roller journaled on the free end of a crank 731 which curves downwardly and forwardly and is fixed on the upper end of a shaft 732 (Figure 11) journaled in a bearing 732a suitably secured to the side edge of the main base 100. The lower end of the shaft 732 has a latch 733 fixed thereon and projecting rearwardly therefrom whose hooked rear end is, at times, moved into engagement with an abutment, stop or pin 734 projecting upwardly from the pawl-carrying slide 712.

The latch 733 is normally urged in a counterclockwise direction in Figure 6 by a tension spring 735, one end of which is connected to the latch 733 and the other end of which is connected to the guide block 713. It is thus seen that the follower 730, on the arm fixed to the upper end of shaft 732, is urged toward the outer surface of the ratchet wheel 676 by the tension spring 735. Accordingly, whenever a notch defined between adjacent cams 677 is aligned with the follower 730 (Figures 3, 10 and 11), the racking drum 317 imparts continuous reciprocatory movement to the bell crank 721 and the pawl-carrying slide 712 to thereby impart step-by-step movement to the improved lower auxiliary pattern drum 230.

However, when the latch 692 is moved out of engagement with the projection 693 on the crank 684, step-by-step rotation is imparted to the speed control pattern wheel or ratchet wheel 676 in the manner heretofore described and, as any one of the cams 677 engages the follower 730, it is apparent that the latch 733 is moved inwardly to occupy the position shown in Figure 6 to thereby prevent a subsequent inactive stroke of the slide 712 so the follower 723 on the bell crank 721 (Figure 3) will not drop into the notches between adjacent cams 331 on the racking drum 317. It will be noted in Figure 3 that the lug 680 depending from the belt shifter 141 is disposed between adjacent cams 677 whenever the follower 730 is engaged by one of the cams 677 so that reciprocation of the pawl 675 is prevented whenever the machine is operating at high speed.

On the other hand, when any one of the cams 677 engages the lug 680 to shift the belt 140 into engagement with the slow speed pulley 132 (Figure 12), the follower

730 is then disposed between an adjacent pair of the cams 677 so the ratchet pawl 675 (Figures 3 and 6) may then be driven at predetermined intervals. The patterning for then controlling reciprocation of the ratchet pawl 675 also comprises a latch or pawl restraining element 740 (Figure 3) whose front end is adapted to, at times, engage a projection or abutment 741 fixed to the medial portion of the lower arm of the bell crank 721.

The rear end of the restraining latch 740 is fixed on the outer end of a shaft 742, to which the lower end of the spring 683 is also connected. The shaft 742 is journaled in the bearing block 326 heretofore described. The other end of the shaft 742 (Figures 10 and 13) has one end of a crank 743 fixed thereon which extends rearwardly and is then bent at substantially right angles and has the lower end of a link 745 pivotally connected thereto. The upper end of link 745 is pivotally connected to the rear end of the substantially horizontal arm of a substantially L-shaped control finger 746 oscillatably mounted on the shaft 701.

The substantially vertical leg or arm of the control finger 746 is aligned with the row of holes 16 in the pattern bar 705 and with the corresponding pattern pins 16a. The lower end of a tension spring 747 is connected to the medial portion of link 745 and the upper end of the tension spring 747 is connected to the spring anchor bar or bracket 708 heretofore described. Thus, in the absence of a pattern pin 16a beneath the control finger 746, the spring 747 urges the restraining latch 740 downwardly in Figure 3 to prevent oscillation of the bell crank 721 and to prevent reciprocation of the pawl-carrying slide 712 and its pawl 675 in Figure 3.

On the other hand, upon a pattern pin 16a (Figure 10) engaging the control finger 746, the control finger 746 moves in a clockwise direction in Figure 13 to impart downward movement to link 745 and crank 743. It is apparent that this will move the shaft 742 in a clockwise direction in Figures 3 and 13 to raise the front end of the restraining latch 740 and to thereby release the bell crank 721 so that oscillation can then be imparted thereto by the racking drum 317 to reciprocate the pawl-carrying slide 712 and pawl 675 to thereby impart step-by-step rotation to the improved lower auxiliary pattern drum 230.

45 Pattern controlled means for raising pattern bar 705

The pattern bar guide 442 is rigidly supported on the frame of the machine by the bracket 226 heretofore described (Figures 13 and 21) and it is also suitably secured to the rear edge of the main base 100. Also, rigidity of the portion of the guide 442 extending above the frame of the machine is assured by means of a diagonal brace 750 (Figures 1, 2, 3, 13 and 14) whose upper end is suitably connected to the medial portion of that portion 55 of the pattern bar guide 442 disposed above the upper cast frame 105 and whose lower end is suitably secured to the front portion of the side deck 105c of the upper cast frame 105.

It will be observed in Figure 21 that the cams 332 on 60 the racking drum 317 successively and intermittently engage a follower 752 on one end of a pawl-carrying bracket 753 which is oscillatably mounted or pivotally mounted, as at 754 (Figures 3, 9, 10 and 13), on the rear upper portion of the bracket 332. The inner end of the pawl-carrying bracket 753, remote from the follower 752, has a pawl 755 pivotally mounted thereon which extends upwardly and whose free end is normally urged toward the teeth in the rack 706 by a tension spring 756.

The rear end of spring 756 is connected to a spring anchor 757 (Figure 10) carried by and extending outwardly from the pawl 755 and the front end of spring 756 is connected to a spring anchor 760 carried by the first of a pair of parallel spaced angle brackets 761, 762 (Figures 3, 13 and 14) suitably secured to the front surface of the pattern bar guide 442. The brackets 761,

762 are parts of a braking mechanism, to be later described, which serves to prevent movement of the pattern bar 705 and rack 706 during each inactive stroke of the pawl 755. In Figure 13, it will be observed that a suitable adjustable bumper 764 is provided which projects from the rear surface of the bracket 323 and limits clockwise movement of the pawl-carrying bracket 753.

Although the pawl 755 reciprocates continuously throughout operation of the knitting machine, it is held out of engagement with the teeth in the rack 706 at predetermined intervals, according to a predetermined pattern, by means of a pattern controlled keeper 766. It will be observed in Figures 10 and 13 that the pawl 755 extends outwardly or is of greater width than the width of the rack 706 so its front surface overlies the rear curved surface of the keeper 766. Thus, the spring 756 also normally urges the reading end of keeper 766 into engagement with the rear surface of the pattern bar 705.

The keeper 766 is aligned with the row of holes 17 and pattern pins 17a. When the reading or upper end of the keeper 766 is in engagement with the rear surface of the pattern bar 705, this permits the pawl 755 to engage the teeth in the rack 706 with each upward stroke thereof to impart a stroke to the pattern bar 705. However, upon any one of the pattern pins 17a being moved upwardly into engagement with the pawl keeper 766, the keeper 766 then moves rearwardly or outwardly relative to the pattern bar 705 and in engagement with the pawl 755 so that with further reciprocation of the pawl 755, it will not engage the teeth in the rack 706.

It will be observed in Figures 10 and 13 that the pawl keeper 766 is in the form of an elongated bar whose lower end is pivotally connected, as at 767, to the upper end of a keeper slide 770 mounted for vertical sliding movement against the rear surface of the gib 704. In this instance, the keeper slide 770 is retained against the rear surface of the gib 704 by means of shoulder screws 771 (Figure 10) which penetrate vertically extending slots 772 formed in the keeper slide 770. The lower end of the keeper slide 770 has a projection 773 thereon which projects outwardly beyond the corresponding edge of the gib 704 and whose upper edge is engaged by one arm of a bell crank 775 (Figures 10 and 13).

The keeper 766 and the keeper slide 770 are normally urged upwardly by a tension spring 776 whose lower end is connected to the upper portion of the keeper slide 770 and whose upper end is connected to the gib 704. It is apparent that, each time the keeper 766 is engaged by a pattern pin 17a, further upward movement cannot be imparted to the pattern bar 705 until the keeper 766 is moved out of engagement with the corresponding pattern pin 17a. Thus, means, under control of the pattern chain 163, imports movement to the bell crank 775 in a clockwise direction in Figure 10 to momentarily move the keeper 766 downwardly. Thus, the pawl 755 is again permitted to move into engagement with the teeth in the rack 706 to impart additional upward movement thereto, after which the bell crank 775 is permitted to move in a counterclockwise direction so the spring 776 returns the keeper 766 to the proper operating level preparatory to a repeat operation.

Now, referring to Figure 13, it will be observed that the bell crank 775 is oscillatably mounted, as at 780, on a bracket 781 suitably secured to the guide 442. The forward arm of bell crank 775 has the rear end of a link 782 pivotally connected thereto which extends forwardly at an angle as shown in Figure 12 and is bent forwardly and the front end of which is pivotally connected, as at 783 (Figures 11, 12 and 13) to the medial portion of a pivoted substantially upright follower-carrying arm 784. The lower end of the follower-carrying arm 784 is pivotally supported on a block 785 fixed to the main base 100 in back of the front run of the pattern chain 163 as shown in Figure 11.

The upper end of the follower-carrying arm 784 has

a tapered follower 786 fixed thereon (Figure 13) and projecting inwardly and downwardly therefrom at an angle. It will be observed in Figure 11 that the pattern chain has a plurality of spaced projections 787 projecting laterally from one side edge thereof, only one of which is shown, and, upon each successive projection 787 moving into engagement with the rear pointed or rounded portion of the follower 786, it is apparent that this will cause the follower 786 to move outwardly as the corresponding projection 787 on the pattern chain 163 moves thereby.

With outward movement of the follower 786, corresponding movement is imparted to the follower-carrying arm 784 and link 782 to thereby momentarily impart clockwise and then counterclockwise movement to the bell crank 775 in Figure 13 for momentarily moving the keeper 766 downwardly in the manner heretofore described. The link 782 preferably has a stop or projection 790 on one side thereof for engaging the front surface of the standard 105a of the upper cast frame 105 to thereby limit rearward movement of the link 782, in the event that the slots 772 (Figure 10) are not of the proper length.

It is thus seen that, notwithstanding the fact that the cams 677 on the pattern wheel 676 prevent the pawl 675 from imparting step-by-step rotational movement to the auxiliary pattern drum 230 during high speed operation of the machine, whenever the pawl keeper 766 (Figure 13) is in engagement with a pattern pin 17a, the pattern bar 705 remains stationary so that operation of the pattern drum 230 is indirectly controlled by the pattern chain 163. Thus, the sequence of operations necessary to effect step-by-step movement of the pattern drum may be stated as follows:

Initially a projection 787 on pattern chain 163 (Figure 11) engages follower 786 (Figure 13) to lower pawl keeper 766 out of engagement with the corresponding pattern pin 17a. Thereupon, the pawl 755, which is continuously reciprocated by the cams 332 on the racking drum 317 (Figure 21), imparts step-by-step advancing or upward movement to the pattern bar 705. Assuming the latches 692 and 740 occupy operative positions as shown in Figures 2 and 3, it is apparent that both of the ratchet pawls 681, 675 would then be stationary.

Accordingly, upon engagement of the control finger 746 by a pattern pin 16a, the latch 740 would be raised out of engagement with the abutment 741 to thereby permit the racking drum 317 to impart reciprocation to the pawl 675 (Figure 6). Reciprocation of the pawl 675 may then continue as long as pins 16a are arranged in immediate succession on the pattern bar 705, although the pawl 755 continues to impart step-by-step movement to the pattern bar 705. Of course, if there is a single pin 16a moved into engagement with the control finger 746, and there are no other pattern pins 16a adjacent said single pattern pin 16a, the keeper 766 may be simultaneously engaged by a pattern pin 17a to prevent further advancement of the pattern bar 705. In this instance, further movement would not be imparted to the pattern bar 705 until a projection 787 on the pattern chain 163 (Figure 11) again moved into engagement with the follower 786.

The advancement of the pattern bar 705 may also be controlled in the manner last described for effecting rotation of the pattern wheel 676 as a pattern pin 15a (Figure 10) moves into engagement with the control finger 746. It is apparent that the length of the pattern bar 705 should be at least sufficient to control the operation of the improved lower auxiliary pattern drum 230 throughout a complete cycle in the operation of the knitting machine, unless it so happens that the arrangement of the pattern pins 15a, 16a, 17a on the pattern bar 705 may be used two or more times during a complete cycle in the operation of the knitting machine or, in other words, during the knitting of a complete article by the knitting machine.

In either event, when the pattern bar 705 has been ad-

vanced upwardly a predetermined distance or to the limit of its upward movement, it is necessary that it be released to permit the same to move downwardly by gravity and to return to its initial position for starting a succeeding cycle in the operation of the machine. Accordingly, it is necessary that the brake means for the pattern bar 705 be released and it is necessary that the control fingers 700, 746, the pattern bar advancing pawl 755 and the pawl keeper 766 be moved rearwardly or outwardly so they are disposed clear of any pattern pins 15a, 16a, 17a and the teeth in the rack 706 during reverse or downward movement of the pattern bar 705. Also, at this time, it is necessary that the pawl 681 does not impart step-by-step rotation to the pattern wheel 676 and it is necessary that the pawl 675 (Figure 6) does not impart step-by-step rotation to the improved lower auxiliary pattern drum 230. Accordingly, the brake mechanism for the pattern bar 705 will now be described in detail.

Brake for pattern bar 705

Referring to Figures 13 and 14, the supporting brake for the pattern bar 705 is broadly designated at 795 and comprises a friction element or disk 796 which loosely penetrates the central portion of the pattern bar guide 442. The rear surface of the friction element 796 bears against the front surface of the pattern bar 705 and pressure is normally imparted thereto by means of an eccentric cam 797 (Figure 13) which is eccentrically mounted for pivotal movement on a shaft 800 fixed in the angle clips 761, 762 heretofore described.

The eccentric cam 797 has an extension or arm 801 extending forwardly therefrom to which the upper end of a link 802 is pivotally connected. The lower end of link 802 is pivotally connected to one end of a lever 803 (Figures 10 and 13) by means of a pin 804 which is pivoted on the corresponding end of lever 803 and is loosely penetrated by the connecting rod 802. The lower end of the link 802 has a collar 805 fixed thereon and a compression spring 806 surrounds the lower portion of the link 802. The upper end of compression spring 806 bears against the pivot pin 804 and the lower end thereof bears against the collar 805 so the cam 797 is resiliently urged against the front surface of the friction element 796 by the spring 806 when the corresponding end of lever 803 is moved downwardly by a cam on the main pattern drum 122, as will be presently described.

Referring to Figures 10, 12, 13 and 35, it will be observed that the lever 803 is oscillatably mounted intermediate its ends, as at 807, on the rear surface of the standard 105a of the upper cast frame 105. The outer end of lever 803 bears against the upper surface of a follower arm or control finger 810 which extends forwardly and is pivotally mounted on the shaft 124 heretofore described. The rear end of the cam follower or control finger 810 is engaged, at times, by the periphery of the main pattern drum 122 and, at other times, the cam follower arm or control finger 810 is engaged by a segmental cam 811 (Figure 35) fixed on the pattern drum 122.

It is apparent that when the cam 811 is in engagement with the follower arm or control finger 810, the end of the lever 803 nearest the observer in Figure 13 occupies a relatively low position to thereby apply pressure to the brake block or friction element 796 (Figures 13 and 14) thereby preventing reverse or downward movement of the pattern bar 705 whenever the pattern racking pawl 755 is not in engagement with one of the teeth in the rack 706. However, when the rack 706 and pattern bar 705 reach the limit of upward movement thereof, the cam 811 (Figure 35) moves out of engagement with the reading end of follower arm 810 thereby permitting the same to move downwardly to raise the end of the lever 803 nearest the observer in Figure 13 and to thereby release the pressure on the friction element 796.

Means to withdraw control fingers away from pattern bar

In order to move the control fingers 700, 746 and keeper 766 out of the path of travel of the respective pattern pins 15a, 16a, 17a and to move the pawl 755 out of the path of travel of the teeth in the rack 706 during reverse or downward movement thereof, it will be observed in Figures 10 and 13 that each of the connecting rods or links 697, 745 has a collar or abutment 813 (Figure 10) thereon which is normally urged against the lower surface of a control finger de-activating element or bar 817 by the corresponding tension springs 707, 747. The connecting rods or links 697, 745 loosely penetrate the control finger de-activating bar 817 so the control rods or links 697, 745 may be moved downwardly and upwardly, as heretofore described, relative to the de-activating bar 817.

The right-hand end of the de-activating bar 817 in Figure 10 is bent downwardly and fixed to one side of a control finger 820 (Figures 10, 13 and 36) which is oscillatably mounted intermediate its ends, as at 821, on a bracket 822 projecting rearwardly from the standard 105a of the upper cast frame 105. The front or reading end of the control lever or finger 820 normally bears against a reduced portion or disk 823 on the inner end of the main pattern drum 122 during normal operation of the pattern bar 705. However, at substantially the time that the pressure on the friction element 796 (Figures 13 and 14) is released, a cam 824 fixed on said disk 823 engages the reading end of the control finger or lever 820 thereby moving the rear end of the control finger 820 and the control finger de-activating bar 817 downwardly in Figures 10, 13 and 36.

It is apparent that this will cause the connecting rods or links 697, 745 to move downwardly, thereby moving the reading ends of the control fingers 700, 746 rearwardly out of the vertical planes of the respective pattern pins 15a, 16a. Downward movement of the de-activating bar 817 also causes the pawl keeper 766 and the pawl 755 to move rearwardly at their upper ends, as will now be described.

In Figures 10 and 13, it will be observed that the de-activating bar 817 is loosely penetrated by a link or connecting rod 825 which has a collar 826 on the lower end thereof. The collar 826 is engaged by the de-activating bar 817, in the course of downward movement thereof, to impart downward movement to the link 825. The upper end of link 825 is pivotally connected to one arm of a bell crank 830 oscillatably mounted, as at 831 (Figure 13), on the inner surface of the bracket 323. The substantially vertical arm of bell crank 825 has a pin or shaft 832 projecting therefrom which is disposed between the medial portion of the keeper 766 and the pattern bar 705. The link 825 is normally urged upwardly by virtue of the tension spring 756 urging the pawl 755 and keeper 766 forwardly or toward the pattern bar 705.

Thus, as the friction element 796 is released, in the manner heretofore described, the downward movement of the de-activating bar 817 not only causes downward movement of the links 697 and 745, but it also causes downward movement of the link 825 to thereby move the pin 832 outwardly in engagement with the medial portion of the keeper 766. Of course, as the keeper 766 moves outwardly, it engages and imparts movement to the upper end of the pawl 755 so that the keeper 766 is moved clear of the pins 17a (Figure 10) on the pattern bar 705 and the pattern bar advancing pawl 755 is also moved clear of the teeth on the rack 706.

It is thus seen that, upon the brake mechanism 795 being released, the pattern bar 705 is free to move downwardly, by gravity. In order to prevent step-by-step rotation of the pattern wheel 676 and the lower auxiliary pattern drum 230 during downward movement of the pattern bar 705, since the latches 692, 740 are moved out of engagement with the respective abutment 693, 741 in Figures 2 and 3 as the reading ends of the control fingers 700, 746 are moved out of the vertical planes of the respective pat

tern pins 15a, 16a, the pawl 681 is raised out of engagement with the pattern wheel 676 (Figure 3) and the pawl 675 (Figure 6) is moved out of engagement with the teeth in the ratchet wheel 652.

To this end, it will be observed in Figures 11 and 13 that the conventionally driven ratchet wheel 162, to which intermittent movement is imparted under control of the pattern chain 163 in a conventional manner, has a cam 835 on the inner face thereof which moves into engagement with a follower or projection 836 on a control lever 837 at substantially the same time that, or slightly before, the reading ends of the control fingers 700, 746 are moved outwardly or rearwardly in the manner heretofore described. The lever 837 is oscillatably mounted intermediate its ends, as at 840, on the standard 105b of the upper cast frame 105 so that engagement of the follower or projection 836 by the cam 835 imparts downward movement to the front portion of the control lever 837.

In so doing, the control lever 837 moves into engagement with the upper end of a substantially vertically disposed bar 841 adjustably secured to a pivot block 842 (Figures 1, 11 and 13) which is pivotally mounted, as at 843, on the front surface of the main base 100. The bar 841 and pivot block 842 are normally urged in a counter-clockwise direction in Figures 1 and 11 by a tension spring 844. The lower end of the pivot block 842 has one end of a link 845 pivotally connected thereto (Figures 1, 3, 6 and 13) whose other end is pivotally connected to one end of a pawl de-activating lever 846 oscillatably mounted intermediate its ends, as at 847, on the guide block 713. The pawl 675 is normally urged toward the ratchet wheel 652 by a tension spring 850 (Figure 6) and has a projection or abutment 851 projecting upwardly therefrom into the horizontal plane of the lever 846.

Thus, as the front end of control lever 837 moves downwardly in engagement with the upper end of bar 841 in Figures 11 and 13, it is apparent that this will impart clockwise movement to the bar 841 and pivot block 842 in Figures 1 and 11, thereby causing the lower end of the pivot block 842 to move from right to left in Figure 6 along with the link 845 and the corresponding end of the de-activating lever 846. Consequently, the rear portion of the lever 846 then engages and imparts outward movement to the abutment 851 to thereby move the pawl 675 out of engagement with the annular ratchet wheel 652 on the upper end of the cylindrical shell 650 of the improved lower auxiliary pattern drum 230.

Referring again to Figure 13, it will be observed that the rear portion of the lever 837 has the lower end of a substantially inverted L-shaped pawl lifting arm 853 pivotally connected thereto, whose upper portion is guided in the upper horizontal portion of an inverted substantially L-shaped bracket 854 (Figures 3 and 13). It will be observed in Figures 2 and 3 that the lower end of the bracket 854 is suitably secured to the open standard 105b of the upper cast frame 105. It is apparent, by referring to Figure 3, that the upper end of the latch lifter 853 will move into engagement with the pawl 681 as movement is imparted to the control lever 837 (Figure 13) by the cam 835 engaging the projection 836.

Thus, the pawl 681 is raised out of engagement with the periphery of the ratchet wheel or pattern wheel 676. Of course, after the pattern bar 705 has moved downwardly to starting position, the cam 835 moves out of engagement with the follower 836 on lever 837 to permit the parts to return to their original positions. Clockwise movement of lever 837 is limited by a heel portion 856 on the rear end of lever 837 engaging the upper surface of the main base 100.

In order to cushion the fall of the pattern bar 705, a cushion device broadly designated at 860, is provided on the lower portion of the pattern bar guide 442 below the level of the improved pattern drum 230, as shown in Figures 1, 2, 22 and 23. Referring to 22 and 23, it will be observed that the lower portion of the pattern bar guide

442 has a slot or opening 861 in the central portion thereof through which a substantial portion of a pivoted friction arm 862 loosely extends. The upper end of the friction arm 862 is pivotally mounted on a shaft 863 journaled in opposed side walls of a substantially U-shaped bracket 864 suitably secured to the front surface of the guide 442.

The lower medial portion of the pivoted friction element 862 has a projection 865 on the front face thereof on which the rear end of a compression spring 866 is mounted. The compression spring 866 extends into a bore or cavity 867 provided therefor in a combination guide and stop member 870. The guide 870 is closed at its front end and the closed front end thereof is threadably penetrated by an adjustment screw 871 having an enlarged portion 872 on the inner end thereof which engages the corresponding or front end of the spring 866 to thereby vary the amount of pressure exerted by the spring 866 and to thereby vary the amount of rearward pressure exerted on the pivoted friction bar or element 862. The guide 870 is suitably secured to or integral with the outer portion of the substantially U-shaped bracket 864.

Now, as the pattern bar 705 is advanced upwardly, it moves above the opening 861 so that the lower rear portion of the friction bar 862 extends rearwardly of the front wall of the guide bar 442. Thus, when the pattern bar 705 is released in the manner heretofore described, it falls against the friction element 862 which then moves in a clockwise direction in Figure 22 due to the weight and impetus of the pattern bar 705. Since the pattern bar 862 is biased rearwardly by the compression spring 866, it is apparent that it will cushion the fall of the pattern bar 705. The pattern bar then finally comes to rest against a stop bar 875 (Figure 22) which closes the lower end of the groove in the rear face of the guide bar 442 and is suitably secured to the guide bar 442.

It is thus seen that I have provided an improved knitting machine having an improved, more compact pattern control means as compared to knitting machines currently in use. It is also seen that I have provided an improved lower auxiliary pattern drum 230 with improved means for controlling the imparting of step-by-step rotation thereof as imparted by the improved pattern bar 705 and intervening connections between the pattern bar 705 and the pattern drum 230 as well as intervening connections between the pattern bar 705 and the pattern chain 163 and the main pattern drum 122. The improved lower auxiliary pattern drum is so arranged as to control substantially all the knitting instrumentalities, thereby greatly simplifying the original setting up of the patterning for the knitting machine and assuring more efficient co-active operation between the various operating parts for the knitting instrumentalities than has heretofore been attainable.

In the drawings and specification there has been set forth a preferred embodiment of the invention and although specific terms are employed, they are used in a generic and descriptive sense only and not for purposes of limitation, the scope of the invention being defined in the claims.

I claim:

1. In a circular knitting machine having knitting instrumentalities including needles, sinkers, means for feeding yarns to said needles and needle cams for controlling the function of said needles, said machine also having a driven pattern chain with different pattern conformations thereon; the combination of a relatively large lower pattern drum mounted for rotation on the lower portion of said machine, first racking means for said lower pattern drum, an elongated pattern bar, second racking means for advancing said pattern bar, means under control of the pattern chain for rendering the second racking means operative and inoperative at predetermined intervals, means under control of said pattern bar for rendering said first racking means operative and inoperative at predetermined intervals, and means under control of said lower pattern

drum for controlling said means for feeding yarns and for controlling certain of said instrumentalities.

2. In a structure according to claim 1 wherein said machine has means for alternately driving the same at relatively slow and relatively high speeds, means operable automatically during relatively high speed operation of said machine for rendering said first racking means inoperative independently of the means under control of said pattern bar.

3. In a structure according to claim 1, means operable automatically upon said pattern bar being advanced a predetermined distance from a starting position for returning said pattern bar to its starting position.

4. In a circular knitting machine having a pattern means; the combination of a pattern drum, a pawl for operating said drum, a vertically movable substantially upright pattern bar, a longitudinally extending rack on said pattern bar, a second pawl for engaging said rack to advance the pattern bar upwardly, means for operating said first pawl to advance said drum, means under control of the patterning on said pattern bar for rendering the means for operating said first pawl operative and inoperative at predetermined intervals, a pawl keeper, means on said pattern bar for moving said pawl keeper against the second pawl at predetermined intervals to hold the second pawl out of engagement with said rack, and means operated by said pattern means for momentarily moving said pawl keeper away from said second pawl for again rendering said second pawl operative.

5. In a circular knitting machine having a plurality of controllable elements thereon and also having a driven pattern means; the combination of an elongated substantially upright guide on said machine, an elongated pattern bar mounted for vertical movement in said guide, an elongated rack carried by said pattern bar, a constantly driven reciprocating pawl for engaging said rack to advance the rack and the pattern bar upwardly, a plurality of vertically extending rows of predeterminedly-spaced projections on said pattern bar, means under control of certain of said projections in certain rows for controlling said controllable elements of the machine, keeper means controlled by the projections in another of said rows for holding said pawl out of engagement with said rack, means restraining said rack from falling whenever the pawl is out of engagement with said rack, and means under control of said pattern means for moving the keeper means to inoperative position relative to said pawl whereby said pawl again advances said rack.

6. In a structure according to claim 5, means operable automatically upon said rack and pattern bar being advanced upwardly a predetermined distance for again rendering said keeper means operative to hold the pawl out of engagement with said rack, means for then releasing the pattern bar from said restraining means to permit said pattern bar to fall, and means limiting downward movement of said pattern bar preparatory to a succeeding cycle in the operation of the pattern bar.

7. In a circular knitting machine having knitting instrumentalities and also having a driven pattern means; the combination of a rotary pattern drum encircling said machine and spaced below said knitting instrumentalities, an elongated substantially upright guide on said machine, an elongated pattern bar mounted for vertical movement in said guide, an elongated rack carried by said pattern bar, a first constantly driven reciprocating pawl for engaging said rack to advance the rack and the pattern bar upwardly, a plurality of vertically extending rows of predeterminedly-spaced projections on said pattern bar, a second pawl, ratchet means on said drum for cooperation with said second pawl, means under control of said projections in one row for reciprocating said second pawl at predetermined intervals, holding means controlled by the projections in another of said rows for holding said first pawl out of engagement with said rack, means restraining said rack from falling whenever the first pawl is out of

engagement with said rack, and means under control of said pattern means for moving said holding means to inoperative position relative to said first pawl whereby said first pawl again advances said rack.

5 8. In a structure according to claim 7, means operable automatically upon said rack and pattern bar being advanced upwardly a predetermined distance for again rendering said holding means operative to hold the pawl out of engagement with said rack, means for then releasing the pattern bar from said restraining means to permit said pattern bar to fall, and means limiting downward movement of said pattern bar preparatory to a succeeding cycle in the operation of the pattern bar.

10 9. A structure according to claim 8 having means to also hold the second pawl out of engagement with the ratchet means during falling of said pattern bar to thereby prevent said means under control of said one row of projections from effecting rotation of said rotary pattern drum.

15 10. In a circular knitting machine having a needle cylinder, knitting instrumentalities and a drive mechanism including a first pattern means; the combination of a second pattern means for controlling predetermined actuation of selected ones of said instrumentalities comprising a rotary pattern drum supported for rotation about a substantially vertical axis about the lower portion of the machine and below the level of said drive mechanism, a third pattern means comprising a vertically movable pattern bar, first and second pawls for rotating the rotary drum and raising the pattern bar, respectively, means under control of the third pattern means to hold the second pawl out of action, means under control of the third pattern means for rendering said first pawl operative and inoperative at predetermined intervals whereby to advance said rotary drum at predetermined intervals, and means under control of said first pattern means to release said second pawl from said holding means.

20 11. In a circular knitting machine having knitting instrumentalities, a frame, a plurality of rotary elements carried by said frame below the knitting instrumentalities, said rotary elements including a driven sprocket wheel and an endless pattern chain engaging said sprocket wheel; the combination of a platform fixed to and encircling the lower portion of said frame below the level of said rotary elements, an improved pattern drum encircling the lower portion of said frame and supported for rotation on said platform about a substantially vertical axis, said pattern drum having indications for controlling the special actuation of selected knitting instrumentalities, opposed reaches of said pattern chain loosely extending through said platform, and means under control of the patterning on said pattern chain for imparting rotation to said pattern drum at predetermined intervals.

25 12. A structure according to claim 11 wherein said machine has means for alternately driving the rotary elements thereof at relatively high and relatively slow speeds, and means automatically operable during the driving of said rotary elements at relatively high speed for rendering the means under control of the patterning on said pattern chain inoperative to thereby prevent rotation of said pattern drum during relatively high speed operation of the machine.

30 13. In a circular knitting machine having a needle cylinder, knitting instrumentalities, a drive mechanism including means for driving said cylinder at relatively high and slow speeds, a ratchet wheel having circularly-spaced cams thereon and means successively engageable by said cams for shifting the cylinder means from high speed to slow speed, said drive mechanism also including a first pattern means; the combination of a second pattern means for controlling predetermined actuation of selected ones of said instrumentalities comprising a rotary pattern drum supported for rotation about a substantially vertical axis about the lower portion of the machine and below the level of said drive mechanism, a third pattern means com-

prising a vertically movable pattern bar, first, second and third pawls for rotating the ratchet wheel and the rotary drum and raising the pattern bar, respectively, holding means under control of the third pattern means to hold the third pawl out of action, means under control of the third pattern means for independently rendering said first and second pawls operative and inoperative at predetermined intervals whereby to advance said ratchet wheel and said rotary drum at predetermined intervals, and means under control of said first pattern means to release said third pawl from said holding means.

14. In a knitting machine having knitting instrumentalities and also having a pattern chain; improved pattern means for controlling predetermined actuation of selected ones of said instrumentalities comprising a rotary annular pattern drum spaced a substantial distance below the level of said knitting instrumentalities, means supporting said rotary pattern drum for rotation about a substantially vertical axis and about the lower portion of said machine, a plurality of arcuately arranged substantially upright control rods supported for oscillation on said machine and having their lower portions disposed closely adjacent the periphery of said rotary drum, control fingers fixed to the lower portion of said control rods and engaging said pattern drum, mechanical connections between the upper portions of said control rods and selected ones of said instrumentalities, an intermediate pattern mechanism movably mounted on said machine, racking means under control of said intermediate pattern mechanism for racking said pattern drum at predetermined intervals, and means under control of said pattern chain for driving said intermediate pattern mechanism at predetermined intervals.

15. A structure according to claim 14 wherein said machine has means for alternately driving the machine at high and slow speeds, means under control of said intermediate pattern mechanism for controlling the intervals at which the machine is driven at said relatively high and slow speeds, and means operable automatically whenever said machine is driven at relatively high speed to render inoperative said means under control of the intermediate pattern mechanism for racking said drum.

16. A structure according to claim 14 wherein said intermediate pattern mechanism comprises an elongated pattern bar, an elongated rack carried by said pattern bar, a driven racking drum, a pawl for engaging said rack and being driven by said racking drum, at least two longitudinally extending rows of predeterminedly spaced projections on said bar, a pawl keeper disposed adjacent said pawl and being engageable by the projections in one row for moving the pawl keeper into engagement with the pawl and to thereby move the pawl out of engagement with said rack, means under control of said pattern chain for moving said pawl keeper out of engagement with a corresponding projection to release said pawl for advancing said rack and pattern bar, a motion-transmitting lever, means resiliently urging one end of the motion-transmitting lever toward the racking drum, means connecting the other end of said motion-transmitting lever to the racking means for the rotary pattern drum, and means under control of the other row of said projections on the pattern bar for selectively restraining the motion-transmitting lever from movement toward the racking drum to thereby render racking means inoperative.

17. In a circular knitting machine having knitting instrumentalities, a needle cylinder, a frame, drive mechanisms in said frame positioned below said needle cylinder and including means for imparting reciprocatory and rotary motion to the needle cylinder at high and slow speeds in alternation, said driving mechanism also including a sprocket wheel, a pattern chain mounted on said sprocket wheel and a main pattern drum driven by said drive mechanism; the combination of a relatively large lower auxiliary pattern drum surrounding the lower portion of said frame and mounted for rotation about

a substantially vertical axis thereon, connections between the lower auxiliary pattern drum and certain of the knitting instrumentalities, a pawl for operating said lower drum, a substantially upright pattern bar, means guiding said pattern bar for vertical movement on said frame, means for intermittently advancing said pattern bar upwardly under control of said pattern chain, means under control of the patterning on said pattern bar for operating said pawl to advance said lower drum, a lever for engaging said pawl to prevent said pawl from operating said lower drum, means under control of said pattern bar for changing the speed of the drive mechanism from high to slow speed and vice versa, means under control of said main pattern drum for restraining said pattern bar from falling and for releasing said restraining means upon said pattern bar being advanced a predetermined distance, means under control of said main pattern drum for rendering said pattern bar advancing means inoperative while said pattern bar is falling, and means under control of said pattern chain for moving said lever against said pawl to maintain said pawl out of engagement with the lower drum while said pattern bar is falling and thereby preventing operation of said lower pattern drum.

18. In a structure according to claim 17, means for rendering the means for changing the speed of the drive mechanism inoperative whenever said lever moves the pawl out of engagement with said lower pattern drum.

19. In a circular knitting machine having a needle cylinder, knitting instrumentalities, a drive mechanism including means for driving said cylinder at relatively high and slow speeds, a ratchet wheel having circularly-spaced cams thereon and means successively engageable by said cams for shifting the cylinder driving means from high speed to slow speed, said drive mechanism also including a first and a second pattern means; the combination of a third pattern means for controlling predetermined actuation of selected ones of said instrumentalities comprising a rotary pattern drum supported for rotation about a substantially vertical axis about the lower portion of the machine and below the level of said drive mechanism, a fourth pattern means comprising a vertically movable pattern bar, a ratchet means on each the rotary drum and the pattern bar, first, second and third reciprocating pawls for operating the ratchet wheel and the rotary drum and advancing the pattern bar upwardly, respectively, means under control of the fourth pattern means to hold the third pawl out of action, means under control of the fourth pattern means for independently rendering said first and second pawls operative and inoperative at predetermined intervals whereby to advance said ratchet wheel and said rotary drum at predetermined intervals, means under control of said first pattern means to release said third pawl from said holding means, means to restrain said pattern bar from downward movement, by gravity, during times in which the third pawl is moving away from the ratchet means on the pattern bar, means under control of the second pattern means for momentarily releasing said pattern bar from said restraining means and for momentarily holding the first, second and third pawls out of action as the released pattern bar moves downwardly by gravity, and means limiting downward movement of the pattern bar.

20. A structure according to claim 19 having means successively engageable by the cams on said ratchet wheel for rendering said second pawl inoperative whenever said driving means operates at high speed and being operable independently of the second and fourth pattern means.

21. In a circular knitting machine having knitting instrumentalities having a needle cylinder, a frame, drive mechanisms positioned in said frame below said needle cylinder and including means for imparting reciprocatory and rotary motion of the needle cylinder, said driving mechanism also including a sprocket wheel and a pattern chain mounted on said sprocket wheel; the combination

of a relatively large pattern drum surrounding the lower portion of said frame and mounted for rotation thereon about a substantially vertical axis, connections between the pattern drum and certain of the knitting instrumentalities, a pawl for operating said drum, a substantially upright pattern bar, means guiding said pattern bar for vertical movement on said frame, means for intermittently advancing said pattern bar upwardly under control of said pattern chain, means under control of the patterning on said pattern bar for operating said pawl to advance said drum, a lever for engaging said pawl to prevent said pawl from operating said drum, means for restraining said pattern bar from falling, means automatically operable upon said pattern bar being advanced a predetermined distance for releasing the pattern bar from said restraining means, means for rendering said pattern bar advancing means inoperative while said bar is falling, and means automatically operable for moving said lever against said pawl to maintain said pawl out of engagement with the drum while said bar is falling and thereby preventing advancement of said pattern drum.

22. In a circular knitting machine having knitting instrumentalities including needles, needle cams, sinkers and means for feeding yarns to said needles, said machine also having a driven pattern chain with different pattern conformations thereon; the combination of a pattern drum, first advancing means for advancing said pattern drum, an elongated pattern bar, second advancing means for advancing said pattern bar, means under control of said pattern chain for rendering the second advancing means operative and inoperative at predetermined intervals, means under control of said pattern bar for rendering said first advancing means operative and inoperative at predetermined intervals and means under control of said pattern drum for controlling certain of said instrumentalities.

23. In a structure according to claim 22 wherein said machine has means for alternately driving the same at relatively slow and relatively high speeds, means operable automatically during relatively high speed operation of the machine for rendering said first advancing means

inoperative independently of the means under control of said pattern bar.

24. A structure according to claim 22 having means operable automatically upon said pattern bar being advanced a predetermined distance from a starting position for returning said pattern bar to its starting position.

25. In a circular knitting machine having knitting instrumentalities including needles, sinkers, means for feeding yarn to said needles and needle cams, said machine having a driven pattern chain with different pattern conformations thereon; the combination of an elongated pattern bar, means under control of the pattern chain for advancing said pattern bar at predetermined intervals, and means responsive to certain movements of said pattern bar for controlling certain of said instrumentalities.

26. A structure according to claim 25 having means operable automatically upon said pattern bar being advanced a predetermined distance from a starting position for returning said pattern bar to its starting position.

27. In a circular knitting machine having knitting instrumentalities including needles, sinkers, means for feeding yarn to said needles and needle cams, said machine having a first pattern means thereon; the combination of an elongated pattern bar, means under control of said first pattern means for advancing said pattern bar at predetermined intervals, and means responsive to certain movements of said pattern bar for controlling certain of said instrumentalities.

28. A structure according to claim 27 having means operable automatically upon said pattern bar being advanced a predetermined distance from a starting position for returning said pattern bar to its starting position.
